Claims priority, application Netherlands Apr. 16, 1958
16 Claims. (Cl. 209—111.5)

The invention relates to a sorting machine. More particularly, it concerns a sorting machine adapted to the sorting or classification of substantially flat documents such as cheques, punched cards, or any substantially flat individual carrier able to enclose or generally support such types of documents, this sorting machine comprising a plurality of sorting stages, each of which has two inputs and two outputs, the inputs of one stage respectively corresponding to the outputs of the preceding stage.

Such a sorting machine is known from U.S. application of J. Young, Serial No. 636,309, filed January 25, 1957. The two inputs of the first sorting stage are initially loaded with the documents to be sorted, these being divided in about two equal loads, one for each input of this first sorting stage. The first sequence of documents in this first input is then merged with the first sequence of documents in the other input, and the merged sequence is directed to one of the two outputs of this first sorting stage and leading to a corresponding input of the second sorting stage. Then, the second sequences respectively appearing at the two inputs of the first sorting stage are similarly merged to produce a second merged sequence which is sent to the other output of the first sorting stage and leading to the corresponding other input of the next sorting stage. Further sequences of like rank at the inputs of the first sorting stage are then similarly merged, the resulting output sequence in each case being directed to the output opposite that taken by the previous merged sequence. The operations at the next sorting stage are exactly similar to those just described and after the documents have passed through a sufficient number of sorting stages, there will be only one output sequence appearing at one of the two outputs of the last sorting stage. The sort is then completed.

In our U.S. patent application Serial No. 805,800, filed April 13, 1959, a sorting machine of this type is also proposed but with the additional characteristic that only two sorting stages are used and forming an endless loop sorting machine. This last machine has many advantages. In particular, it takes a limited amount of space since only two simultaneously working sorting stages are needed. Also, whereas the sorting machine of the type disclosed in the above application, Serial No. 636,309, necessitates a number of cascaded sorting stages which is at least equal to $\log_2 N$, with N representing the maximum number of documents required to be sorted by the machine, in the second above mentioned machine, the fixed number of two looped sorting stages can serve in all cases for any number N of documents to be sorted, the only limitation being sufficient space on the two pairs of conveyors linking the two sorting stages, to permit the documents to be accommodated thereon. Also, the time of sorting now depends on the number of sorting passes which are needed and not on the time needed for the documents to pass through the maximum number of cascaded sorting stages. This would be the case in the earlier machine since even if the actual sort is finished as the documents start to flow from one output of an intermediate stage, these documents will nevertheless have to be passed, without actually being sorted, through the

2

remaining sorting stages until they are finally delivered by the last one. It will be clear that the number of required sorting passes is in itself dependent on the initial distribution of the documents to be sorted and also on the number of documents fed to the sorting machine, i.e. the less documents there are, and the nearer is their initial distribution to the desired one, the shorter will be the sorting time. Hence, a very flexible and efficient sorting machine is available.

10 With the two-stage looped sorting machine described above, upon the sort being finished, the documents can only circulate through one particular input for each of the two stages, said particular inputs of course corresponding to particular outputs of the other stage to which they are linked by two pairs of conveyors. Hence, this state of affairs, i.e. absence of documents travelling on one conveyor out of each pair, can be detected, and steps can be taken to recognize the first document in the endless single file of documents going round the two stages, whereby the machine can be stopped with the sorted documents in the required order. However, some time will be required for the recognition of this final desired state of affairs.

25 A general object of the invention is to provide such a two-stage sorting machine with two markers which can be sorted with the documents, and preferably have the same shape, and which markers can be used to foresee the end of the sort at such a time that upon the final single output sequence of documents being delivered by 30 a sorting stage, the sorting machine is made ready for the sorted documents to be taken out, thereby avoiding time losses and a number of unnecessary sorting passes.

Another object of the invention is to avoid the insertion of the two markers into the sorting machine every 35 time a sorting operation is about to begin, the two markers being instead initially stored into the sorting machine and being returned to their initial storage positions at the end of the sort after having performed their functions. Then, during subsequent sorting operations they will automatically be made to leave their storage positions as the sort starts.

40 In accordance with a feature of the invention, a sorting machine comprising two sorting stages, each with two inputs and two outputs, the two inputs of one stage being respectively fed by the two outputs of the other stage and vice versa, with the articles to be sorted initially applied to the two inputs of a sorting stage in series of substantially equal sizes and sorted through each stage in 45 accordance with their sorting characteristics, e.g. by merging sequences of like rank appearing at the two inputs and dispatching the merged sequences alternately to one and the other output of the sorting stage, is characterised by the fact that each lot of articles, e.g. documents or 50 document carriers, fed to the sorting machine is accompanied throughout the sort by two markers adapted to go through said two sorting stages in the same way as the articles, said markers being respectively placed behind two series of articles initially applied to the two inputs of a sorting stage, and each of the electrical control circuits for said two stages being adapted to recognize said markers and to always dispatch them to opposite outputs.

55 In accordance with another feature of the invention, a sorting machine as characterised above, is further characterised in that upon a first marker reaching a sorting stage, it stays there under the control of the electrical control circuit for the corresponding stage while the eventual sequences of documents remaining at the input of said sorting stage opposite the one entered by the first 60 marker, are alternately dispatched to one and the other output of said sorting stage until the second marker reaches said sorting stage, said two markers then being 65

dispatched through said sorting stage, one towards one output and the other towards the other output.

In accordance with another feature of the invention, a sorting machine as characterised above, is further characterised in that, at the beginning of a sorting operation, said two markers are initially in respective storage positions in one of two sorting stages, to which they will be automatically returned after the sort is completed.

In accordance with another feature of the invention, a sorting machine as characterised above, is further characterised in that for said one stage initially containing said two markers, these are only dispatched to the two outputs of said one stage under the control of the electrical control circuit for said one stage upon there being at least one article reaching one of the two inputs of said one stage, and that means are provided to stop said articles from flowing through the other stage upon the sort being completed, whereby upon the final single sequence of articles having been delivered through said one stage, said two markers will be returned to and stay in their initial storage positions.

In accordance with yet another feature of the invention, a sorting machine as characterised above is further characterised in that the electrical control circuits for said one stage in which the two markers are initially stored is provided with a sequence counter reset each time said two markers pass said one stage and adapted to count the number of output sequences from said one stage between two successive passages of said two markers through said one stage, and more particularly to establish whether no more than four output sequences have flowed through said one stage during a round trip of said two markers, whereby upon said sequence counter indicating no more than four output sequences, on their way to the corresponding inputs of the other stage, stop means will be operated after said markers have gained access to said other stage but prior to the articles behind said markers being allowed to go through said one stage, whereby the final output sequence of articles will be prevented from passing through said other stage and may be positioned ready to be taken out of the sorting machine.

The above and other objects and features of the invention and the best manner of attaining them will be better understood from the following description of a detailed embodiment to be read in conjunction with the accompanying drawings which represent:

FIG. 1, a diagram illustrating the principle of a two-stage sorting machine;

FIG. 2, a diagram showing a cheque carrier in one of the four reading positions of the sorting machine;

FIG. 3, a block diagram of the complete electrical control circuits used for each of the two stages of the sorting machine;

FIG. 4, synchronized operating circuits used for each of the two sorting stages; and

FIGS. 5 and 6, with the latter on the right of the former, the electrical control circuits for each of the two stages of the sorting machine.

FIG. 1 illustrates the principle of operation of a two-stage sorting machine of the type disclosed in our U.S. application, Serial No. 805,800. The normal sorting stage NS includes two input positions A₄ and B₃ which terminate two corresponding input lanes formed by transverse conveyors each comprising two parallel chains adapted to support and advance cheque carriers 1 of the shape shown in FIG. 2 by their two lateral extensions 2 and 2'. Thus, the carriers 1 containing the cheques, such as 3, after having been advanced, will eventually be pressed against the input position A₄ or B₃ as the continuously moving chains then slide under their lateral extensions from which positions they will be laterally dispatched by edgewise conveying rollers to the respective next positions A₃ and B₂. Position B₂ already constitutes the reading position in which a carrier 1 is shown in FIG. 2. On the other

hand, position A₃ is merely an intermediate position due to the input position A₄ being fed from the outside A lane.

As the transparent cheque carrier 1 enters the reading position B₂, or A₂ which follows A₃, the piece of magnetic tape 4 which is made part of the cheque carrier 1 and which contains the relevant information pertaining to the cheque 3, will pass across a fixed reading head 5.

Each reading position is provided with an individual photocell arrangement. As the cheque carrier 1 enters the reading position A₂ or B₂, photocell 6 will have its beam of light interrupted by the piece of magnetic tape 4. This produces a signal which recognizes the presence of the piece of magnetic tape. This is conveniently used to enable a distinction between the ordinary cheque carriers and the special markers which are used to control the sorting operation. In fact, these markers are simply ordinary transparent carriers which do not contain a cheque and from which the piece of magnetic tape has been removed so that photocell 6 can discriminate them. Only two of such special marking carriers are needed irrespective of the number of ordinary cheque carriers to be sorted. In the normal case, with the carrier moving in the direction of the arrow, after the piece of magnetic tape 4 has interrupted the beam of light of photocell 6, the upper opaque part of the cheque carrier 1 and more particularly the front extension 2' will obscure photocell 7. This signal is used to create a so-called reading authorization which is applied to the electronic control circuits of the sorting machine which are adapted to compare the account numbers of successive cheques of one series to ensure that they are sorted in the right manner. These electronic control circuits are fully described in our U.S. application, Serial No. 805,841, filed April 13, 1959.

At the time that front tip 2' obscures photocell 7, part 35 8 of the magnetic tape 4 which actually registers the signals is not yet under the fixed reading head 5. As the carrier 1 progresses, the reading head 5 will now read the signals 8 and these will be able to reach the electronic control circuits. Yet another photocell 9 will afterwards be obscured by front tip 2' and this signal will be used to suppress the reading authorization for the electronic control circuits. This reading authorization permits the isolation of the electronic control circuits from any spurious pulses except during the time the useful information is actually read. Photocell 9, used to stop the reading authorization, plays no part with regard to the electrical control circuits which will be described, but photocells 6 and 7 are used to distinguish between normal and marking carriers, the latter controlling the sorting operation. Whereas photocells 7 and 9 produce an activating signal upon their illumination being suppressed, the opposite is true for photocell 6 which therefore normally delivers an activating signal in the absence of a carrier. But, this activating signal from photocell 6 is gated by that 50 produced by photocell 7, whereby a marking carrier will be detected by the joint action of photocells 6 and 7 (lighted) and 7 (obscured).

From the reading positions A₂ and B₂, the carriers are next moved into the merging positions A₁ and B₁ from 60 which the two parallel A and B paths are merged into one. This will permit only two output positions per sorting stage, i.e. C and D.

The test made by the electronic comparator will determine if an A carrier or a B carrier is to be advanced 65 out of the sorting stage and either into the output position C or D.

The sorting machine is arranged to function stepwise under the control of cyclic pulses. During each cycle or step, a carrier in one of the positions shown may be advanced to the next position, as the eventual preceding carrier leaves. For the output positions such as C or D, the advancement during one cycle to the corresponding next position D or E may of course be replaced by a displacement onto the corresponding output conveyor. 70 From the reject positions E or E', which the carriers are

allowed to reach if, due to some fault they are not allowed to go on either output conveyor, they are automatically taken out of the sorting closed circuit and merely dropped into a corresponding reject container (not shown). During normal operation, the five positions such as A₂-A₄, B₂ and B₃ for the normal sorting stage NS, are generally each filled with a carrier, while at the same time there may be a carrier in one of the merging positions A₁ or B₁ and further carriers in positions C, D or E.

A carrier in any of the five positions such as A₁, B₁, C, D or E for the normal sorting stage NS, will automatically be advanced during a cycle without any further control except in the case of the output positions C or D, wherefrom the carrier can be directed to the corresponding output transverse conveyor by the electronic comparator.

For the five other positions of the stage, the advancement during a cycle of either the cheques in positions A₂-A₄ or the cheques in positions B₂, B₃ will be determined by the electronic comparator.

The reverse sorting stage RS of the machine is identical to the normal sorting stage NS described above and the corresponding positions have been indicated in FIG. 1 with the same references provided with a prime, e.g. input position A'₄ corresponds to input position A₄.

The machine will be initially loaded on the two input conveyors leading to the normal stage NS and more particularly to the input positions A₄ and B₃. The input load of cheques should preferably be about evenly divided between the two lanes to ensure that the two halves include about the same number of sequences, and that a maximum number of sequences of the same rank on each of the input sides have already a chance to be merged during the first sorting passes through the normal stage NS. The markers which play an essential part in facilitating the sorting operation are "built in," to ensure that they will always be there at the right place at the beginning of a sorting operation. More particularly, when the machine is about to be used, one of the two markers is included in the reading position A'₂ of the reverse sorting stage RS, while the other marker is included in the other reading position B'₂ of that stage.

A dotted line has been drawn across the lanes leading to A₄ and B₃ to indicate the presence of stop members which may be used to prevent the cheque carriers resting on corresponding conveyors from being actually advanced to the input positions A₄ and B₃ by the already moving conveyor chains until start signals are given to the electrical control circuits. The loaded cheque carriers, e.g. batches of 500 on each of the two input lanes leading to A₄ and B₃ are initially deposited on conveying chains in front of these stop members controlled from a relay Zcr (FIG. 5) and the operation of which will later be described. When this relay is operated as is normally the case before a sorting operation, the stop members prevent the roller extensions 2 and 2' (FIG. 2) of the front cheque carrier from advancing and the conveyor chains merely slide under the bottom parts of these extensions 2 and 2' of all the cheque carriers stacked before the stop members.

As the machine is started, relay Zcr is released, the stops which it controls are raised and the two batches of cheque carriers are driven towards and slightly above the input positions A₄ and B₃. The cheque carriers will now be made to advance through the normal sorting stage NS which will perform a first sorting pass.

Initially, as the machine is started, the markers in the reading positions A'₂ and B'₂ and one of which must come behind the batch of cheque carriers leading to position A₄ while the other must come behind the other batch of carriers leading to position B₃, are not yet advanced. As will be described later in detail, this is only permitted upon the first cheque of one of the two input batches having gone through the normal sorting stage NS and reaching one of the input positions B'₃ or A'₄ of the re-

verse sorting stage RS. At this moment, the markers will be able to advance through RS, one being lifted from the output position C' and the other being lifted from the output position D'.

- 5 During every sorting pass, such as the first one through NS, the cheques are advanced until one of the input lanes, e.g. leading to input position A₄, no longer contains any cheques but merely the marker. This means that an equal number of sequences have now been taken from the two inputs, have been merged in pairs, and have been distributed alternately to the input lanes leading to the input positions A'₄ and B'₃ of the reverse sorting stage RS. On these last output lanes will therefore appear only about half the number of sequences initially present on the two lanes leading to A₄ and B₃. As the cheques reach the input positions A'₄ and B'₃, they are immediately passed into the reverse sorting stage RS whereby both stages will soon be functioning actively at the same time. Upon one of the markers reaching the input position, such as 10 A₂ the remaining sequences on the input lane leading to B₃ will be alternatively sent to the input lanes leading to A'₄ and B'₃ respectively. Hence, if the batch of carriers on one side initially contains p sequences while the batch of carriers on the other side contains q sequences, with 15 20 $p > q$, the normal sorting stage NS will deliver p sequences equally divided (to the nearest integer) between its two outputs. Therefore, after the first sorting pass through NS, the two batches of cheques presented to the two input positions A'₄ and B'₃ of RS will either contain exactly 25 30 the same number of sequences

$$\frac{p}{2}$$

if p is even, or

$$\frac{p+1}{2}$$

- 35 if p is odd. The first pass has reduced the total number of input sequences from $p+q$ to p , and the remaining sorting passes will each time reduce the number of sequences 40 by half, with the usual allowance when the total number of input sequences is not even.

- 45 Each time a marker has reached an input position such as A₄, it goes into the following reading position such as A₂ to be detected so that it may act upon the corresponding electrical control equipment, as outlined above, to make the residual sequence in the other input flow through the sorting stages concerned in such a manner that it will be alternately distributed between the two outputs leading to the other sorting stage. In fact, after the 50 first sorting pass, in normal circumstances there may only be at most one such residual sequence in the other input. When the second marker reaches the other reading position such as B₂, the corresponding control equipment for the stage concerned will now take care of sending the 55 two markers one towards one input of the other stage and the other towards the other input, with the proviso that for the reverse sorting stage RS, this only takes place upon there being at least one cheque ready to enter one of the input positions A'₄ or B'₃.

- 60 The electrical control equipment for the reverse sorting stage RS contains a sequence counter which is adapted to count the number of sequences between two successive passages of the two markers through this reverse sorting stage. This counter is reset as the two markers 65 are sent out from the reverse sorting stage RS. If, when the two markers arrive in the reading positions A'₂ and B'₂, the counter indicates that no more than four output sequences have been distributed to the two outputs through positions C' and D', the batches of cheques going 70 respectively to the input positions A₄ and B₃ will, at most, each be divided into two serial sequences. Accordingly, the normal sorting stage NS will then deliver at most one sequence through C and at most one sequence through D, whereby at the next passage through the reverse sorting stage RS the eventual two sequences of cheques, one

flowing through B'_3 and the other through A'_4 , will be merged into the single final desired sequence at the output of the reverse starting stage RS, the sorting operation being thus terminated.

This beforehand knowledge by the sequence counter that the sorting operation will be terminated after another double pass through NS and RS may be used to advantage not only to avoid unnecessary "sorting passes," but also to avoid the final output sequence flowing at one of the outputs of RS from again reaching one of the input positions A_4 or B_3 . The front cheque could be stopped there in front of and above the input position A_4 or B_3 but it would then be relatively difficult to position a take out mechanism for removing the sorted batch of cheques from the sorting machine.

As soon as the sequence counter finds that there have not been more than four sequences through RS upon the two markers being positioned in A'_2 and B'_2 respectively, the corresponding control equipment for RS sends out the two markers towards A_4 and B_3 respectively.

But, from the moment the two markers are sent out of RS, a timing mechanism will be started to operate relay Zcr after a time sufficient to ensure that both markers have passed the respective stops located on the conveyors paths somewhat ahead of A_4 and B_3 and controlled by this relay, so that the markers can still follow their respective batches of cheques. In this manner, as the cheques will be delivered by RS during the final sorting pass, they will not be allowed to proceed beyond the stops and the take out mechanism can readily lift out the sorted batch of cheques from the machine upon the sort being completed.

It will be appreciated that the cheques are loaded in the input lanes leading to the normal sorting stage NS and they also always appear on these lanes at the end of the sorting operation, which means that the same mechanism can be used to deposit them on the conveyors chains at the beginning of the operation and to lift them out from the conveyors chains at the end of the sort. Moreover, so that the same containers can be used to feed the cheques into the machine and to take them out, the control equipment for the reverse sorting stage RS is also adapted to make one special forced switch-over of the output during the last sorting pass so that the sorted single sequence of cheques is about evenly divided into the two lanes. In this way, the two half batches of sorted cheques will be found, at the end of the sorting operation, in the same respective positions as the two unsorted half batches of cheques were initially put. To this end, the control equipment RS, as it controls the last sorting pass, takes care that the last final sequence of cheques is sent out from output position D' , and a line has been shown to cross the output lane from D' to indicate that a photocell apparatus is arranged to react upon about half the total of cheques now passing against the stops on the lane leading to input position A_4 . This photocell arrangement controls the release of the output relay Odr for the reverse stage RS, whereby the release of this relay causes the remaining cheques now to flow out of RS through the other output position C' .

An additional advantage of the sequence counter for RS is the following: normally as the first cheque of a series coming through one input reaches the corresponding reading position such as B'_2 for the reverse sorting stage RS, this first cheque is read, and the control equipment now takes care to advance the cheques on the other input leading to the corresponding reading position A'_2 until a cheque enters this position and is read. If the sequence counter for RS, as the two markers are positioned into the corresponding reading positions A'_2 and B'_2 , detects that there has not been more than two output sequences, one is certain that these two sequences will be merged into one by next going through the normal sorting stage NS which will therefore deliver only the single finished sequence at one of its outputs C or D. Hence, the

sort is already completed in such a case, but it is convenient that the cheques should still travel through RS so that they will eventually always reach the same positions to be taken out of the machine. However, the final sequence coming out of say output position C would see its first cheque reach the corresponding reading position B'_2 and be stopped there until one cheque comes into the reading position A'_2 . Since the sorting operation is finished at the output of NS, one would have to wait until the complete series of cheques had passed through the output position C of NS, to finally see one of the two markers, sent out through output positions C and D, reach the input position A'_2 where it could be recognized and permit the finished single sequence to flow out of RS. The sequence counter can be made to prevent such a state of affairs. Upon having detected that there had been no more than two sequences flowing out of RS, as the cheques flowing out through only output position C or output position D arrive at the reading positions B'_2 or A'_2 , the control equipment for RS will cause them to be passed immediately towards the output position C' without waiting for a cheque, i.e. one of the markers, to arrive in the reading position A'_2 . In this way, despite the facility of always having the sorted cheques delivered at the output of RS, a possible delay amounting to a sorting pass is avoided.

The details of the above operation will now be described.

Considering FIG. 3, the complete electrical control equipment MJS' for the reverse sorting stage RS is shown to comprise two main circuits: the control circuit CL and the synchronizing circuit SY, respectively shown in detail in FIGS. 5 and 6, and in FIG. 4. The control equipment MJS for the normal stage NS is identical to circuit MJS' except that the connections in dotted lines are not used for the normal sorting stage, but exclusively for the reverse sorting stage. Some of the terminals of CL which are not interconnected with terminals of SY are shown connected to various other terminals which are not part of the electrical control circuits to be described, but belong to electronic control circuits which are the subject of our U.S. application, Serial No. 805,841. For the purpose of the present description, it will be sufficient to assume binary signals at these terminals, the times of change in value of these signals being defined in the description. The circuits such as MJS' also include various keys which have auxiliary functions to be defined later, except K_2 which is a general starting key for the sorting stage concerned. The two contacts of key K_2 permit the connection of terminals CL_{14} and CL_{15} to the push button contact K_0 and to the key contact K_1 respectively. Depressing push button K_0 will permit the momentary application of ground to the terminals CL_{14} both in MJS' and in MJS upon the respective master keys K_2 having been operated. This reset operation should be made before starting a sorting operation or whenever a fault has occurred and the machine is restarted, in the course of a sorting operation. After push button K_0 has been depressed, the general master starting key K_1 may now be thrown to apply ground to terminals CL_{15} both in MJS' and in MJS and again through the master keys K_2 for the stages concerned.

Before describing the operations following the successive application of ground to terminals CL_{14} and CL_{15} with reference to the detailed circuits of FIGS. 5 and 6, the synchronizing circuit SY provided for each stage of the sorting machine and detailed in FIG. 4, will be outlined.

At the bottom of FIG. 4 are shown the various electromagnets which control the advancement and the positioning of the cheque carriers during their edgewise translation movements from the input position A'_4 or B'_3 to the output positions C' , or D' or eventually to the ejecting position E' .

Each of the ten positions, except the reject position E'

which need not be provided with any controlling electromagnets, includes a so-called shift electromagnet such as SA₄ for the input position A'₄, etc., up to SD for output position D'. When operated, a shift electromagnet permits the application of a driving roller (not shown) against the cheque carrier, which driving roller in conjunction with an opposite idling roller will permit advance of the cheque carrier out of the position concerned so that it enters the next position in which further advancement to permit a correct centering of the cheque carrier in that next position, will be made under the control of a fixed pair of rollers one of which is a driving roller.

The various positions, except A'₄, B'₃ and E' also include so-called positioning electromagnets such as PA₃ for position A'₃ etc., up to PD for position D'. These positioning electromagnets control a catch member which arrests the front edge of a cheque carrier near the end of the corresponding position, as its rear edge leaves the fixed pair of rollers at the entrance of this position. Thus, as a cheque carrier is driven out of the input position such as A'₄ under the control of SA₄ and travels through the next position A'₃ under the further control of the fixed rollers at the entrance of A'₃, it will finally be arrested in that last position and properly centered by the positioning electromagnet PA₃ in the released condition. The operations are cyclic, and during the next cycle of advancement for the A' input, the positioning electromagnet PA₃ will first be operated to permit the cheque carrier to move out of A'₃ as soon as the shift electromagnet SA₃ is subsequently operated. The positioning electromagnet PA₃ will only be released after the cheque carrier is already fully engaged in the next position A'₂ in which it will be arrested and properly centered by the release of the corresponding positioning electromagnet PA₂.

Apart from the nine shift electromagnets and the seven positioning electromagnets, there are also a pair of so-called drop electromagnets DA and DB, and a pair of so-called lift electromagnets LC and LD.

When operated, the former are used to control a mechanism dropping the first cheque carrier abutting against and slightly on top of the input position such as A'₄ and which was driven there by the continuously moving conveyors interconnecting the two stages of the machine. This input mechanism is fully described in the application of G.X. Lens et al., Serial No. 806,286, filed April 14, 1959. Thus, when a cheque carrier is to be advanced through the reverse sorting stage RS and for instance through the input position A'₄ prior to the operation of the shift electromagnet SA₄ the drop electromagnet DA will first be energised to cause the first cheque carrier to be dropped into position A'₄. This is only a transit position, and during the same cycle of operation, the subsequent energisation of SA₄ will already be propelling the first cheque carrier into the next intermediate position A'₃ in which the cheque carrier will already be found, correctly centered, at the end of the cycle.

The latter electromagnets LC and LD will be respectively energised towards the end of the cycle so that a cheque carrier having reached the output position C' for instance, will be lifted out of this position and onto the corresponding output conveyor leading to input position B₃ of the normal sorting stage NS. It should be noted that the action of the lift electromagnet such as LC is merely a liberating action which makes the cheque carrier ready to be lifted out, but the actual lifting operation by means of a constantly rotating takeout mechanism fully described in the Belgian Patent No. 577,765, will only take place towards the end of the cycle, when the cheque carrier is already at rest and correctly positioned in the output position C'.

Each of the seven positions which are provided with a positioning electromagnet, i.e. all positions except the input positions A'₄, B'₃ and the reject position E', also include two microswitch contacts such as kx, one at the entrance of the position and one towards the exit. These

contacts are normally open, and upon the cheque carrier having travelled into the position and having been arrested therein, these two contacts should still be open if the cheque carrier is properly positioned. All these contacts are connected in parallel and thereby afford a means for operating an error relay Er if at the end of the cycle at least one of these is still closed indicating that the cheque carrier is badly positioned. Then, the cyclic advancement of the cheque carriers is automatically stopped preventing damage to these and to the sorting machine.

As shown in FIG. 4, all the 20 electromagnets so far described have one end of their windings directly connected to battery, while their other ends may be connected to a common ground provided at break contact e₁ through various cam contacts such as PT₁ which are cyclically closed during various intervals of time to permit the operation of the electromagnets to which they are connected, such as the positioning electromagnets PC and PD connected to make contact PT₁.

A full cycle of the various cyclic pulses used to operate these electromagnets is represented in the figure. To give an idea of the times involved, advancement of the cheque carriers at the rate of 3 per second corresponds to a cycle of about 330 milliseconds. The beginning of each cycle starts with a pulse PU due to the closure of contacts PU₁-PU₃ and transferring the ground at break contact e₁ to terminals SY₃-SY₅. These pulses reach terminals CL₁₉-CL₂₁ and are used as probe pulses for examining the condition of circuit CL so as to normally drive a pulse either at terminal CL₃₃ connected to terminal SY₉, or at terminal CL₃₄ connected to terminal SY₁₀, and also derive a pulse at terminal CL₃₇ connected to terminal SY₇, or at terminal CL₃₈ connected to terminal SY₈. The first pulse either at terminal SY₉ or at SY₁₀ determines whether the cheque carriers in the A positions or in the B positions should be advanced. Either relay Ar or Br which have one end of their windings directly connected to battery therefore receives temporarily the ground at break contact e₁ which is applied momentarily to the corresponding terminal SY₉ or SY₁₀. The relay, such as Ar locks to ground through its make contact a₁ in series with the interrupter contact IN₁ in the break position and break contact e₁. Thus, the relay indicating which input should be advanced will remain locked in the operated condition until the end of the cycle, the time at which the interrupting pulse IN will occur, corresponding to the opening of the break interrupter contact IN₁ which is transferred to the make condition. It is at this moment, the end of the cycle, that the operation of make interrupter contact IN₁ will ascertain that none of the 14 positioning contacts such as kx are closed. If any such contact is closed, relay Er operates through an obvious circuit, change over contact e₁ moves over to the make condition to suppress the ground which can be momentarily applied to the various electromagnets and which is also used to operate or hold some other relays. At the same time, the closure of make contact e₁ locks the error relay Er to ground, this relay having no sufficient time to de-energise during the change over action of contact e₁.

At this moment, the cyclic closure of the various cam contacts providing the different controlling pulses will be without effect and the faulty sorting stage is stopped until the cheque carrier which is wrongly positioned is removed from its incorrect position thereby reopening the closed contact(s) kx and releasing relay Er to return to the normal operating conditions.

The operation of an input relay such as Ar closes a series of make contacts A₂-A₇ whereby the drop pulses provided by the closure of the corresponding cam contact DR₂, the shift pulse provided by the closure of the corresponding cam contact SH₃ and the positioning pulse provided by the closure of the corresponding cam contact PT₄ can respectively be caused to energise the corresponding drop electromagnet DA, shift electromagnets SA₂

and SA_2 and positioning electromagnets PA_2 and PA_3 . It should be noted however, that the closure of the cam contact DR_2 can only be effective to operate DA upon Ar being energised, if make contact ka is also energised.

This make contact ka is a micro-switch contact which is only operated upon there being at least one cheque carrier abutting against and on top of the corresponding input position A'_4 . This is to ensure that the cheque carrier coming from the input conveyor is properly positioned before being acted upon by the input dropping mechanism controlled by the drop electromagnet DA . Thus, if relay Ar is operated at the beginning of a cycle, during the cycle, the various cheque carriers on the A side will all be advanced simultaneously, one being replaced by the next. This is also true for the merging position A'_1 , since for the latter, the shift and positioning electromagnets SA_1 and PA_1 are directly controlled by the corresponding pulses due to the closure of the contacts SH_2 and PT_2 . Obviously, the operation of relay Br would advance the cheque carriers on the corresponding B input side.

When the two markers have reached their respective reading positions A'_1 and B'_2 , a slightly different operation is required at the inputs. At the beginning of the cycle, the ground input pulse at terminal SY_5 which reaches terminal CL_{19} , will not reappear either at terminal CL_{33} or CL_{34} , but at terminal CL_{35} or CL_{36} which are respectively connected to terminals SY_{11} or SY_{12} . In such a case, relay $A'r$ will be operated instead of relay Ar , or relay $B'r$ will be energised instead of relay Br . These relays control only the reading positions A'_2 or B'_2 which means that only the two markers will be successively advanced during the corresponding two cycles, the upstream cheque carriers temporarily remaining in their respective positions, i.e. the intermediate position A'_3 or the positions as first cheque carriers of the input series next to the input positions A'_4 and B'_3 . The reason for this special advancement limited to the markers is to avoid a complication in the electrical control circuit and which will be discussed later in the description. After the two markers have been dispatched, normal advancement of all the carriers on the A side, or of all the carriers on the B side is resumed.

The pulse at the beginning of the cycle and delivered at terminal SY_4 to reach through CL either terminal SY_7 or SY_8 , depending on whether the cheque carrier to be advanced is to be lifted out from position C' or D' or should be allowed to reach the reject position E' , will either operate the clutch electromagnets CC or DC . These clutch electromagnets control a mechanical memory device which will store the output to which the cheque carrier is to be directed until the cheque carrier is in the corresponding output position C' or D' ready to be lifted out onto the corresponding output conveyor. At the time the pulse at the beginning of a cycle operates CC or DC , the cheque carrier is in the reading position A'_2 or B'_2 from which it will be taken out during the cycle. But, depending on whether the cheque carrier is to leave to the C or to the D output, it will only arrive in the output position C' or D' two or three cycles afterwards. Thus, it is necessary to memorize the output direction of the cheque carrier during two or three cycles since during the next cycle after the cheque carrier has left the reading position, normally another cheque carrier will take its place and it will again be required to energize either CC or DC to indicate the direction to be taken by this new cheque carrier. Hence, the electromagnet, such as CC , which also locks to ground through its make contact cc_1 will be energised only during part of the cycle and will have its holding circuit interrupted by the special interrupter pulse SI corresponding to the opening of break contact SI_1 . It will be noted that this special interrupter pulse is required in view of the construction of the mechanical memory which necessitates a release of CC or DC rather well before the end of the cycle, as shown by the time position of interrupter pulse SI . This

mechanical memory may be of the construction fully detailed in Belgian Patent No. 577,759. It consists in mechanical detents having two stable positions and mounted on a wheel, a revolution of which defines three

cycles, such as one illustrated in FIG. 4. The operation of either CC or DC will trigger a corresponding detent as it passes along and the operated detent will be used to momentarily close either the make contacts PC_1 or the make contacts PD_1 at times shown by the pulses PC or PD . The contact PC_1 and PD_1 are respectively positioned near the periphery of the rotating mechanical memory, so that PC_1 will be closed one cycle after the operation of CC while PD_1 is positioned so as to be closed two cycles after the operation of DC . This is one cycle less than the total memory time required, and this is due to PC_1 or PD_1 being closed at the beginning of a cycle, when the carrier has still to be advanced by one position, whereas the relay Cr or Dr , operated by PC_1 or PD_1 , respectively, acts to control the lift electromagnets after 20 the carrier has moved again. Hence, the pulses PC and PD never occur simultaneously but only one of these can be present during a cycle. The make contacts PC_1 or PD_1 are used to operate either relay Cr or Dr through obvious circuits, the operated one of these relays locking 25 through its make contact, such as c_1 , to the ground provided through the interrupter break contact IN_1 . During the subsequent lift pulse LI in the cycle corresponding to the operation of the relay, such as Cr , the lift electromagnet, such as LC , will be operated through make contact c_2 to place the carrier on the C output lane. Otherwise, one cycle later the carrier would be found in position D and through make contact d_2 , LD would lift it out onto the D output lane. If due to some faulty operation, neither the electromagnet CC or DC is energized, two and three cycles later, neither relay Cr nor relay Dr will be operated and consequently the carrier will be allowed to flow into the ejecting position E from which it will be automatically dropped by gravity into a reject container.

Shift make contact SH_1 on the other side of the ground provided at break contact e_1 is connected to terminal SY_6 either through make contact a_6 or make contact b_6 . Thus, upon either relay Ar or Br having been energised to advance the A or the B cheques, the subsequent shift pulse SH which follows the disappearance of the pulse PU at the beginning of the cycle and which operated Ar or Br , will appear at terminal SY_6 , connected to terminal CL_{18} to perform various functions in the electrical control circuit CL , one of which being to generate a suitable starting pulse for the electronic comparison circuit.

The description of a sorting operation will now be made with particular reference to FIGS. 5 and 6. It is assumed that power has been applied, that the four transverse conveyors are in movement, that the machine delivers the various cyclic pulses required and explained above, that the two conveyors leading to input positions A_4 and B_3 of the normal sorting stage NS are filled with carriers each containing a cheque and to be sorted with the account numbers in an order of increasing significance, and that the two markers are in the reading positions A'_2 and B'_2 of the reverse sorting stage RS . Therefore, the shift electromagnets SA_1 , SB_1 , SC and SD , as well as the positioning electromagnets PA_1 , PB_1 , PC and PD are already cyclically operated by the corresponding SH and PT pulses. Also, relays Iar and Odr may be operated or not in both stages of the machine depending on whether respective activating signals are present at terminals CMP_1 and CMP_3 (FIG. 3) which are respectively connected to terminals CL_{11} and CL_{12} leading to one end of the windings of Iar and Odr through the respective amplifying devices IA and OD , the other ends of Iar and Odr being connected to +210 volts. As shown for the reverse sorting stage, the direct connection between terminals CL_{13} and OD and which is marked with a cross should be replaced by the dotted line connection through break contact zc_2 of relay Zcr . For

the reverse sorting stage, relay Zcr controlling the stops, was normally energised at the end of the previous sorting operation to stop the sorted cheques and initially it is therefore still locked through its make contact zc_1 and break contact sa_9 . Therefore, in the reverse sorting stage relay Odr cannot be initially operated. The amplifying devices IA and OD may each consist of a pentode with its grid connected to the input terminal, such as CL_{11} , and limited to a fixed bias voltage, the winding of the output relay, such as Iar , being inserted between the plate of this tube and the anode supply of $+210$ volts. A sufficiently positive signal to energise relay Iar or Odr will be provided from the electronic comparison circuit as long as the comparator indicates that the A input should be advanced thereby operating Iar , or indicates that the D output should be used thereby operating Odr . The initial potential conditions at terminals CL_{11} and CL_{12} are in fact immaterial.

With reference to FIG. 2, since the two markers are in the reading positions A'_2 and B'_2 of the reverse sorting stage, light is cut off from the corresponding photocells 7 as for any carrier in the reading position, but light is still allowed to illuminate the photocells 6, since the empty transparent carrier used as a marker does not bear a piece of magnetic tape which in a normal carrier would obscure this photocell 6. The photo-cell arrangements of the photocells 6 normally obscured by any other carrier in the reading position, have their outputs connected to terminals CL_6 and CL_7 for reading positions A'_2 and B'_2 , respectively. Each photocell may be connected in the grid circuit of a triode and have one end biassed to a negative potential so that when it is illuminated, the triode is cut off, whereas it becomes conductive when light is suppressed by the opaque upper part of the carrier reaching the reading position. This input triode may be used as a cathode follower of which an output leads to the electronic comparison circuits after being combined in a mixer with a similar output from the other reading position, and to provide a reading authorization to the electronic control circuits as the inscribed part of the magnetic tape of the cheque carrier is about to go past the fixed reading head. On the other hand the cathode output of the input triode may be connected via a further triode cathode follower whose output drives the grid of a pentode arrangement similar to that used for IA and OD.

Therefore, for the reverse sorting stage only, relays Aar and Bar are initially operated.

Upon the reset push-button K_0 being depressed, for both sorting stages, ground will reach terminal CL_{14} and the Sar relays will be operated. Break contact sa_1 temporarily opens, and any of the six $Xar-fr$ relays which might initially be operated are instantly released. These relays constitute a counter of 3 which is used to count successive rejects, a pair of these relays, such as Xar , Xbr , being used for each of the three counter stages. This counts only consecutive rejects to stop the machine after three such rejects. Every time a cheque is incorrectly sorted, this reject counter makes one step and every time a cheque is correctly sorted, this reject counter is released by the operation of relay Okr opening break contact ok_1 . At the temporary opening of break contact sc_2 , relay Rkr which might be initially operated and locked through this contact in series with its make contact rk_1 is forced to release. This relay Rkr is operated through make contact rk_1 of relay Rjr which may itself be operated whenever a cheque is rejected, the operation of Rkr serving to light an indication lamp (not shown) to draw attention to the fact that there has at least been one reject at the sorting stage concerned. At make contact sa_3 , ground is applied to relay Sbr which operates, but only as long as relay Sar remains energised by the depression of the reset push-button K_0 . The temporary operation of relay Sbr applies ground to the mixer M_1 which ground appears at the output of this mixer as an

activating signal for the gates G_2 and G_3 whose other inputs are connected to terminals CL_2 and CL_4 respectively through the amplifier devices AB and BB. Terminals CL_2 and CL_4 are connected to the photo-cells 6 (FIG. 2) which are normally illuminated and remain so only when a marker, and not a cheque is in the corresponding reading position. These photo-cells are included in the grid circuit of a cathode follower triode in such a way that they normally provide a sufficiently positive signal at the grid to make the triode conductive, the latter being driven to cut off only when the light is interrupted. Therefore, these photo-cells connected to terminals CL_2 and CL_4 normally provide an activating signal at the output of the devices AB and BB.

15 The markers in the reading positions A'_2 and B'_2 of the reverse sorting stage leave those signals and consequently the temporary operation of Sbr will produce pulses at the outputs of G_2 and G_3 which reach the amplifying devices AB' and BB' respectively through the mixers M_2 and M_3 . The amplifying devices AB' and BB' are similar to IA already described and consequently, relays Abr and Bbr will both be operated for the reverse sorting stage only since make contacts aa_1 and ba_2 are closed. The operation of relays Abr and Bbr closes the make contacts ab_1 and bb_1 which apply ground respectively to the mixers M_2 and M_3 . As the activating pulses at the outputs of G_2 and G_3 are also constituted by ground pulses, the permanent ground conditions now supplied by contacts ab_1 and bb_1 are therefore used to latch the corresponding relays Abr and Bbr . Contacts ab_1 and bb_1 apart from applying holding grounds to the mixers M_2 and M_3 , also apply ground, through the respective decoupling rectifiers RA and RB, to terminals CL_1 and CL_5 respectively connected to terminals MLA_{15} and MLB_{15} (FIG. 3) of the electronic control circuit. Therein, these activating signals are used as substitute positioning signals. Indeed, when a normal cheque carrier is read by the electronic comparison circuit, care is taken to verify that the numerical information read is correctly positioned in a shift register. This correct positioning is responsible for authorizing a probe pulse to scan the actual comparator. The positioning of the information should be simultaneously correct in the two shift registers which are respectively used for the A and the B input. Therefore, if a cheque is read while the other reading position is occupied by a mark, the entrance of which has caused the previous information to be pushed out of the corresponding shift register, the signal at terminal CL_1 or CL_5 can therefore be used as a substitute positioning authorization.

50 In operating, relays Abr and Bbr for the reverse sorting stage, also open their break contacts ab_2 and bb_2 whereby the potential of -250 volts connected to terminals CL_{30} and CL_{31} respectively through resistors R_1 and R_2 is disconnected. Terminals CL_{30} and CL_{31} lead to terminals CMP_{15} and CMP_{21} of the electronic comparator (FIG. 3). Therein, they lead respectively to two bistable devices part of the actual comparator and respectively indicating if the account number of an incoming cheque on the A(CL_{30}) or on the B(CL_{31}) side is larger or smaller than the account number of the cheque which is being pushed out of the corresponding reading position. This connection of resistor R_1 or R_2 can be used to effectively increase the value of a potentiometer resistance part of a bistable multivibrator so as to reverse the state of the latter. These particular resets are carried out so that the bistable devices will both indicate that the previous account number is higher than that of the cheque which has just entered the reading position. Thus, whenever a marker comes into a reading position, the comparator is made to react in such a way that the bistable device indicates the interruption of the sequence on the input side corresponding to that marker, which means that only the cheques on the other

input side may eventually continue to build the outgoing sequence.

Normally, an activating ground prevails at terminal CL₂₆, being connected through break contacts ab_3 and bb_3 in series. This terminal is connected to terminal IPC₂₂ (FIG. 3) of the electronic control circuit and the activating signal thereat is normally used to permit recirculation of the account numbers stored in both shift registers of the sorting stage concerned. As a cheque is being read and its account number is serially fed into the corresponding shift register, it is compared with the account number of the previous cheque on that side and which is being simultaneously pushed out of that shift register. But, after this comparison has been performed, the newly sorted account number will now be compared with the account number already and still stored in the other shift register corresponding to the other input. This comparison will again be done serially by causing both shift registers to be looped on themselves and make a full cycle of recirculation.

Whenever a marker has reached the reading position, it must stay there until the other marker also reaches the other reading position. The residual sequence(s) of cheques preceding the second marker must merely be alternately distributed to the two outputs. Therefore, the account numbers of these residual cheques need not be compared with the last account number stored in the shift register for the other input. Recirculation is unnecessary, and the eventual interruption(s) of the sequence(s) of these residual cheques are simply detected at the serial comparison between one cheque and the preceding one on the same side. Hence, upon a marker reaching a reading position, ab_3 or bb_3 opens whereby -25 volts, which is the standard inhibiting potential for the gates of the electronic control circuit is now connected to terminal CL₂₆ through resistance R₃ instead of the activating ground potential.

At make contacts ab_4 and bb_4 in series, when both markers are in the reading positions an operating circuit is closed for relay Mar of the reverse sorting stage, through a circuit including also break contact m_1 of relay Mr which cannot be operated since the serially connected break contacts ab_5 and bb_5 are opened. Relay Mar locks through its make contact ma_1 to ensure that it will only be released upon both markers having left the reading positions thereby operating relay Mr. Through make contact bb_6 , a circuit is established for the operation of relay Djr, which circuit in the case of the reverse sorting stage also includes break contact mh_4 . In operating, relay Djr moves its change-over contact dj_1 to the make position thereby connecting the armature to terminal CL₃₃. This is however, without effect at this moment since break contact ma_3 opens the connection on the other side of the armature.

A further consequence of the momentary operation of relay Sbr is to open break contact sb_2 to ensure the release of relay Olr which may be initially locked through its make contact ol_1 . In fact, for the reverse sorting stage only, the operating circuit of this relay is interrupted by the opening of break contact ma_{10} as long as relay Mar is operated. Finally, the opening of break contact sb_3 interrupts the connection of -250 volts which, through resistor R₄, is connected to terminals CL₂₇ and CL₂₈. Again, for the reverse sorting stage only, this connection is also opened at break contact ma_3 as long as relay Mar is operated.

Terminals CL₂₇ and CL₂₈ are respectively connected to terminals CMP₁₆ and ACC₁₀ (FIG. 3) of the electronic control circuit, the former connection extending through key K₆ in the released condition. This is a reset operation for bistable devices included in the electronic control circuits and carried out in the same manner as already explained in connection with the opening of the connections to terminals CL₃₀ and CL₃₁. Terminal CMP₁₆ leads to the bistable device of the electronic comparator indicat-

ing whether the A or B input should be advanced. The opening of the connection at terminal CL₂₇ will cause this bistable device to indicate that the A input should be advanced. Terminal ACC₁₀ leads to two other bistable devices in the electronic control circuit and which must be reset in well defined conditions prior to the beginning of a sorting operation and more generally prior to the beginning of a sorting pass starting each time the two markers are in the reading positions of the sorting stage concerned (ma_3 opened).

When both markers are in the reading positions of a stage, not only must a new sequence be started, but also, since the end of a sorting pass has been reached, a definite set of starting operations must be performed, since when reading the following cheques one must take care that their account numbers are not effectively compared with the account numbers of the last two cheques which preceded the markers on each side and the account numbers of which are still stored in the respective shift registers. Indeed, the markers, bearing no piece of magnetic tape with synchronising pulses to advance the shift registers, were not able to push out these last two account numbers. This will be done by the reading of the cheques following the markers but with the help of the reset signals at terminals CL₃₀ and CL₃₁, the comparator will be made to discard the actual comparisons.

Relay Mar being operated for the reverse sorting stage only, at break contact ma_2 it interrupts the circuits of relays Olr and Err which are respectively connected to terminals CL₉ and CL₁₀ through the amplifying devices OK and ER which are similar to IA already described. These last two terminals are respectively connected to terminals CMP₁₀ and CMP₆ of the electronic comparator. Each time a new cheque has been read, an end of comparison pulse of about 60 milliseconds appears at terminal CL₉ to operate relay Olr. On the other hand, if after recirculating the two account numbers stored in the respective shift registers, these are not properly positioned therein, a pulse of 60 milliseconds will instead appear at terminal CL₁₀ to operate the error relay Err. The subsequent closure of make contact er_1 closes a temporary operating circuit to energize relay Sbr, through terminal CL₁₇, key K₄ and terminal CL₁₆. The action is similar to that which occurs at the beginning of a sort, and since relay Olr does not operate, both carriers are then rejected in turn. The purpose of opening break contact ma_2 is to ensure that the electronic control circuits cannot in any way, e.g. spurious pulses triggering, cause an incorrect control of the two markers when these are both in the reading positions of one stage. At that moment, it is essential that these two markers should be sent to opposite outputs and the electrical relay control circuits are solely responsible for this action.

At make contact ma_7 , a connection between terminals CL₁₉ on the one hand and CL₃₅ or CL₃₆ is prepared to cause the subsequent advancement of the two markers.

A further consequence of the momentary operation of relay Sar, is the closure of the make contacts Sa₄₋₇ leading respectively to the relays Yar, Ycr, Yer, Ygr via the respective break contacts yb_1 , yd_1 , yf_1 , yh_1 . These four relays together with their respective helping relays Ybr, Ydr, Yfr and Yhr constitute a counter of four, which is the sequence counter used only for the reverse sorting stage, to determine the end of a sorting operation. In operating, the four counter relays such as Yar lock to ground through their make contacts such as ya_1 , the winding of their associated helping relay such as Ybr, and break contact dn_2 which is connected to terminal CL₂₅ itself connected to ground through key K₃ in the released condition. Since the operation of relay Sar is only temporary, upon its release, the opening of the contacts such as sa_4 leads to the operation of the four helping relays such as Ybr which are now locked in series with their associated relays such as Yar. In this condition, the sequence counter indicates that the complete load of cheques

still comprises more than four sequences and consequently that more than a single round trip through the sorting machine is still necessary to obtain the finished sorted load of cheques. At the beginning of the sorting operation, such as is now described, this is evidently an arbitrary assumption, since the number of initial sequences into which the load of cheques is divided has not yet been ascertained to be greater than four, as the cheques have not yet been passed through the reverse sorting stage. This assumption is however, quite justified since, with loads of about one thousand cheques to be sorted, on the average these will initially be divided into five-hundred sequences necessitating nine sorting passes. The chances that there would be no more than four sequences initially are therefore extremely remote and even then one could not complain for taking four sorting passes since this is still below the average number of sorting passes required.

Actually, if a mere merging of two loads of cheques is desired, or if it is believed that the two loads initially feeding the two inputs of the normal sorting stage are already sorted, the merging key K_3 provided for the control equipment of the reverse sorting stage may be operated to ensure that only a single round trip will be made. This will later be described.

Relay Y_{gr} of the sequence counter being operated, it will be remarked that relay M_{gr} has no opportunity to be energised upon the release of relay S_{ar} closing break contact sa_9 when make contacts ab_9 and bb_9 are already closed.

A last consequence of the temporary operation of relay S_{ar} is the opening of break contact sa_9 which releases the operated Z_{cr} relay, whereby the stops provided along the lanes leading to the input positions A_4 and B_3 of the normal sorting stage are raised to allow the carriers deposited on these lanes to be advanced towards and against these input positions ready to enter them.

The sorting operation will now be started by permanently depressing key K_1 to apply ground at terminal CL_{15} thereby energising relays S_{cr} in both sorting stages. The operation of relay S_{cr} results in applying the start of cycle pulses regularly appearing at terminals CL_{19} , CL_{20} and CL_{21} to various circuits through the respective make contacts sc_1 , sc_2 and sc_3 .

A pulse passing through make contact sc_1 is applied to terminal CL_{33} for the normal sorting stage only, through break contacts rl_1 , ma_8 , st_1 and dj_1 in the make position. Indeed, for the normal sorting stage, relay D_{jr} must certainly be operated since the bistable of the electronic comparator defining which input should be advanced now indicates the A input and consequently relay I_{ar} is operated closing an operating circuit for relay D_{jr} through make contact ia_1 . The pulse at terminal CL_{33} reaches terminal SY_9 and relay Ar (FIG. 4) is operated and locked. Contact ka (FIG. 4) is closed by the first carrier next to input position A_4 and therefore the drop pulse DR energises electromagnet DA to drop the first carrier in input position A_4 from which it is shifted as soon as electromagnet SA_4 is operated by the shift pulse SH . The carrier is further advanced through position A_3 in which it will be arrested towards the end of the cycle at the end of the positioning pulse PT causing the release of electromagnet PA_3 to stop the cheque carrier in position A_3 .

As make contact SH_1 is closed (shift pulse), ground is applied to terminal SY_6 through make contact a_8 and it reaches terminal CL_{18} to flow through the windings of relays S_{dr} and S_{ar} in parallel. The first of these relays is however, slow to operate, and consequently relay S_{ar} will operate first through break contact sd_1 , this relay S_{ar} releasing as soon as S_{dr} is energised, and the latter falling back at the end of the shift pulse SH . The purpose of this circuit arrangement is to restrict the time during which S_{ar} is operated to an interval substantially shorter than that of the shift pulse SH , since at its break

contact se_2 , relay S_{ar} causes the initial release of relay O_{lr} , but must allow this relay to be eventually re-energised if the electronic comparison has been correctly performed. This may well take place before the end of the shift pulse SH .

On the other hand, the operation of relay S_{ar} by the shift pulse SH which starts after the pulse PU subsides, is useful to ensure that break contact ol_2 is not prematurely released. Indeed, this contact is connected to make contact sc_3 receiving a start of cycle pulse PU , and this pulse PU should only be able to reach terminal CL_{39} , and the reject counter, if during the previous cycle relay O_{lr} did not operate thereby indicating a fault. Then before relay O_{lr} is automatically reset to the released condition, the fact that it did not operate should be recorded by the reject counter, but the mere reset of O_{lr} should of course not produce such a reject pulse.

The temporary operation of relay S_{ar} is used to provide a ground pulse at terminal CL_{32} through resistor R_5 . This terminal CL_{32} is connected to terminal IPC_4 of the electronic control circuits (not shown). This pulse is used as a starting signal for the electronic control circuits. Various reset operations will take place in these circuits before the first cheque carrier on the A input leading to the normal sorting stage NS has had an opportunity to generate a reading authorization pulse for the electronic control circuit by the front tip of the cheque carrier obscuring photocell 7 (FIG. 2). However, during the first cycle beginning with the operation and the latching of relay Ar (FIG. 4) the first cheque carrier on the A input to the normal sorting stage will merely be advanced through the input position A_4 to be positioned in the intermediate position A_3 at the end of the cycle, the various electromagnets operating in the manner previously described. At the end of this first active cycle, interrupter contact IN_1 will move to the make position to release relay Ar .

At the beginning of the second cycle, the start of cycle pulse PU will again flow between terminals CL_{19} and CL_{33} through make contact dj_1 of the operated relay D_{jr} . Therefore, relay Ar (FIG. 4) will again be operated and locked to cause the second cheque carrier on the A input to be advanced through input position A_4 and to be positioned in the intermediate position A_3 , while the first A carrier is simultaneously advanced from this last position to the reading position A_2 , by the shift pulse operating SA_3 (FIG. 4).

During this advancement of the first A cheque, it will thus be read and relay Aar will be energised. The closure of make contact aa_1 is ineffective to operate relay Abr , since a normal cheque carrier and not a marker has been read. Also, the closure of make contact aa_2 comes after the start of cycle pulse passing through make contact sc_3 , and accordingly, this start of cycle pulse will not be able to pass through break contact ol_2 of relay O_{lr} which is still released, to incorrectly produce a reject pulse to the counter of 3.

The electronic control circuits are so arranged that upon the first A cheque having been read, the bistable device controlling which input side should be advanced, will now be automatically set to the B side whereby the signal at terminal CL_{11} disappears. Consequently, relay I_{ar} releases and due to the opening of make contact ia_1 , relay D_{jr} releases also.

At the end of the second active cycle, relay Ar will therefore again be released, but at the beginning of the third active cycle the start of cycle pulse appearing at terminal CL_{19} will now flow to terminal CL_{34} and from there to terminal SY_{10} to energise relay Br which locks. Despite relay Aar being still operated and make contact aa_2 closed, since change-over contact ia_2 is now in the break position, the start of cycle pulse at terminal CL_{21} will still be unable to cause an undesired reject pulse through break contact ol_2 . During the third active cycle, due to the operation of relay Br , the first cheque carrier

on the B input will be advanced, through input position B₃ to be positioned at the end of this third cycle into the reading position B₂, and after having been read, relay Bar will be energized.

This time, the first B cheque will be compared, in the electronic control circuit, with the first A cheque and if the comparison proceeds normally, an end of comparison pulse of 60 milliseconds will be produced by the electronic comparator at terminal CMP₁₀ connected to terminal CL₉ to cause the temporary operation of relay Okr. The operation of relay Okr has always two effects: at break contact ok₁, ground is disconnected from the reject counter of 3 so that if one or more stages of this counter had previously been operated, they are now released since the function of this reject counter is to count consecutive rejects only; secondly at make contact ok₂, ground is applied to relay Olr which operates and locks through its make contact ol₁. Make contact ok₂ also applies ground to the armature of change-over contact od₁. At the beginning of a sorting operation, relay Odr may be operated or not. Its initial condition is however immaterial, since only the changes of output controlled by this relay matter. Assuming that relay Odr is initially released for the normal sorting stage, as make contact ok₂ closes, relay Car is operated to indicate that the first outgoing cheque should go to the C output. Relay Car will be maintained energised through make contact ol₁ during the remainder of the cycle.

At the beginning of the fourth output cycle, the start of cycle pulse at terminal CL₁₉ will now reach terminal CL₃₃ or CL₃₄ depending on whether after reading the first B cheque, the electronic comparator found that its account number was larger (lar and Djr operator) or smaller (lar and Djr released), respectively than that of the first A cheque, and the cheque with the smallest account number will, during this fourth cycle, be advanced to the merging position A₁ or B₁ while the other cheque remains in the reading position B₂ or A₂, respectively, the cheques on the A side advancing behind the first. The start of cycle pulse at terminal CL₂₀ will now be able to pass through make contact ca₁ to reach terminal CL₃₇ connected to terminal SY₇. Therefore, the electromagnet CC controlling the mechanical output memory previously outlined, will be operated and locked through its make contact cc₁ in series with the special interrupter contact SI₁. The mechanical memory will therefore be set so that one cycle afterwards, a pulse PC will be produced by the closure of make contact PC₁. Otherwise, if relay Odr had been operated, relay Dar and the electromagnet DC would have been energised, resulting this time in the production, two cycles afterwards, of a pulse PD by the closure of make contact PD₁. Two or three cycles are needed for the first cheque in the A₂ or B₂ reading position, to be respectively located in the output position C or D. But although the closure of PC₁ or PD₁ energises relay Cr or Dr while the first cheque carrier is still in one of the merging positions or in the C output position respectively, the lift pulse LI, exploiting, by the closure of make contact LI₁, the closure of make contact c₂ or d₂ to energize LC or LD, does so after the carrier has made a further step.

At the normal sorting stage NS, the sorting operations described will proceed on the principle of merging sequences of like ranks on both inputs of the normal sorting stage, the merged sequences being alternately sent to one or the other output of the normal sorting stage.

As soon as the first cheque carrier to come out of the normal sorting stage has travelled through the transverse conveyor either linking output position C to input position B'₃ of the reverse sorting stage RS, or the output position D or to input position A'₄ of the reverse sorting stage RS, the two markers initially positioned in the reading positions A'₂ and B'₂ of that reverse sorting stage will be sent away behind the two lots of inputs cheques.

Indeed, upon the first cheque carrier being placed next

to input position A'₄ or B'₃ ready to be advanced through these respective positions, either make contact ka or kb (FIG. 4) will be closed. Hence, the drop pulse DR produced by the closure of make contacts DR₂ and DR₁ will apply a ground pulse either at terminal SY₂ or SY₁. These pulses are respectively connected to terminals CL₂₂ or CL₂₃ and consequently, either relay Adr or relay Bdr will be temporarily energised. Hence, during the drop pulse DR, either make contact ad₁ or make contact bd₁ will be closed to apply ground from make contact ma₁ to relay Dmr through make contact ab₁₀. This ground is also applied to relay Mbr and finally, through make contact ma₆ to relay Dar. As a consequence, these three relays Dmr, Mbr and Dar are all energised simultaneously. Relay Mbr locks to ground through its make contact mb₁ in series with make contact ma₁, and therefore, the ground connection coming through this last make contact is now applied to changeover contact ab₁₀ independently of make contacts ad₁ and bd₁ which are now bridged by make contact mb₁. This is to maintain this ground connection independently of the operation of relay Adr or Bdr which immediately release upon the disappearance of the drop pulse DR.

During the next cycle following that which saw the operation of either relay Adr or Bdr subsequent to the arrival of first cheque carrier to the reverse sorting stage, the start of the cycle pulse at terminal CL₁₉ will therefore pass to terminal CL₃₅ through make contacts sc₁, ma₇ and dm₁ in series. Terminal CL₃₅ being connected to terminal SY₁₁, this ground pulse will operate relay A'r which locks in the same way as the ordinary relay Ar. As will be seen from FIG. 4, relay A'r only controls the positioning electromagnet PA₂ through its make contact a'₃ and the shift electromagnet SA₂ through its make contact a'₂. Hence, when the two markers are in the reading positions such as A'₂, B'₂ for the reverse sorting stage RS, when they are successively made to leave these positions, the electromagnets controlling the upstream positions such as A'₃, B'₃ and A'₄ are not energised, contrary to what happens if the normal input relays Ar or Br are energised instead of A'r or B'r. The reason for this slightly modified action is the following: Normally, cheque carriers may be present in the upstream positions such as A'₃ and B'₃. Hence, if upon the first marker in the A reading position being sent away, the following cheque carrier on that side is allowed to replace said marker in the reading position, it will be read in the normal way by the electronic control circuits and as required, a check will be made to ascertain that the account number of the cheque is correctly positioned in the shift register and that there has been no abnormal disparity between the duplicate normal and inverse forms of recording which may be used as a safeguard. If a fault is recorded for this first cheque following the outgoing marker, it will be necessary to send that cheque carrier to the reject position. Therefore, at the time that the other marker is still in the reading position, the other reading position would be occupied by a cheque carrier which must be sent to the reject position. Normally, this cheque carrier would immediately be advanced through the sorting stage concerned and by replaced by a new one. If this normal procedure is adopted, special memorizing circuits will have to be provided to take care of remembering that the second marker, still in the reading position, must yet be dispatched on the output side opposite that taken by the first marker. Alternatively, the normal procedure of immediately sending the second marker after the first and towards the opposite output, could be followed. But in such a case, special memory circuits should again be provided to remember that the cheque carrier in the reading position must later go to the reject position. Thus, in such a case, the normal simple routines of the machine would be upset, and the proposed solution of simply using relays A'r and B'r to temporarily hold the continuous advancement until the

two markers have been dispatched, is a preferred simple solution.

During the next cycle following that which saw the operation of either relay A_{dr} or B_{dr} , the marker in position A'_2 will therefore be dispatched to merging position A'_1 , on its way to the D output, since relay D_{ar} has been operated. Upon this first marker leaving the reading position, photocell 7 (FIG. 2) is no longer obscured whereby relay A_{ar} releases and by opening its make contact aa_1 , it releases the locked relay A_{br} which in turn, by opening its make contact ab_1 , interrupts the ground condition applied at terminal CL , through rectifier RA towards the electronic control circuit. Due to the release of relay A_{br} , relay D_{mr} releases and instead, relay D_{nr} energises through make contact ma_4 and due to the ground still provided through make contact ma_1 in series with make contact mb_1 . In this circuit, but through the additional make contact ma_5 , relay Car energises as well.

Hence, during the cycle following that during which the first marker was sent away, the start of cycle pulse at terminal CL_{19} will reach terminal CL_{38} through make contacts sc_1 , ma_7 and dn_1 in series. This time, this will lead to SY_{12} and the operation of relay B'_r . Likewise, the start of cycle pulse at terminal CL_{20} will now reach terminal CL_{37} through make contacts sc_2 and ca_1 in series, taking care of the dispatch of the second marker to the C output, since electromagnet CC (FIG. 4) will now be activated.

As the second marker leaves the reading position B'_2 , relay B_{ar} releases and forces relay B_{br} to release with corresponding results to those already described in relation to the departure of the first marker. Apart from the resistors R_1 and R_2 being again both connected to terminal CL_{30} and CL_{31} leading to the electronic comparator and whereby normal comparisons between an incoming cheque and the one it replaces on the same side can now be made, break contacts ab_3 and bb_3 being both closed, authorizing ground is again applied to terminal CL_{26} to permit the simultaneous recirculation of the two numbers stored in the two shift registers of the electronic control circuit, so that these two numbers can be serially compared.

As far as the electrical control circuits are concerned, the immediate result of both relays A_{br} and B_{br} being released is the operation of relay Mr through break contacts ab_5 and bb_5 in series. This last relay opens the locked operating circuit of relay Mar at break contact m_1 , whereby relay Mar releases and in opening make contact ma_1 , causes the joint release of relays M_{br} , D_{nr} and Car .

It is to be noted that as a result of the temporary operation of relay D_{nr} during the cycle corresponding to the dispatch of the second marker, break contact dn_2 was temporarily opened. Consequently, the ground normally provided and acting as holding ground for the sequence counter of 4 was momentarily interrupted, resulting in the joint release of the eight counter relays $Tar-Yhr$. The departure of the two markers therefore leads to the reset of this sequence counter to the zero condition from which it is now ready to count the number of outgoing sequences from the reverse sorting stage RS .

Due to the release of relay Mar , resistor R_4 is again connected to terminals CL_{27} and CL_{28} leading to the electronic control circuits which are now ready to start with the comparison of the cheques which now follow the two markers through the reverse sorting stage. Thus, the electronic control circuits for the reverse sorting stage are ready to make the second sorting pass at the same time that the first sorting pass is being performed by the normal sorting stage. Due to the opening of contacts ma_4 , ma_5 and ma_6 , the output relays Car and D_{ar} are now disconnected from the control circuit which initially led to the dispatch of the two markers, and from now on these relays will only be controlled in the normal manner by the electric control circuits (ok_2) until the two markers

having made a round trip are again to be found in the reading positions, thus after the two sorting passes, one through each stage and carried out simultaneously. The reopening of make contact ma_7 prevents a further operation of the special input relays A'_r and B'_r , while the closure of break contacts ma_8 and ma_9 again permits the appearance of the start of cycle pulses at terminal CL_{33} or CL_{34} , and eventually in case of an error causing a reject, at terminal CL_{39} . Finally, the closure of break contact ma_{10} makes relay O_{lr} ready to be energised after each successful comparison.

During the cycle which follows the departure of the second marker from its reading position B'_2 in the reverse sorting stage, the first cheque carrier next to input position A'_4 , if it is there, will be advanced through this input position. Otherwise, if there are only one or more cheque carriers accumulating against the input position B'_3 , these will have to wait until the first cheque carrier of the second output sequence delivered by the normal sorting stage arrives to close contact ka . The operations will then be identical to those already described as happening initially at the input of the normal sorting stage: first the A cheques will be advanced until the first can be read, and then the B cheques will be advanced to permit a comparison between the first A and B cheques, after which comparison sorting through the reverse sorting stage proceeds normally in the manner already described.

As the cheques are sorted through a stage, one marker will eventually reach the reading position leading to the operation of relay A_{br} or B_{br} . This means that all the cheques on the corresponding input side have gone through the sorting stage concerned, and it is now required that the cheques eventually remaining on the other input side should be automatically dispatched through the sorting stage, which should only detect the ends of input sequences on that side, so that these eventual cheques or residual sequences of cheques on one side can be evenly distributed between the two outputs of the sorting stage. Assuming for instance that relay A_{br} operates, ground transmitted by make contact ab_1 to terminal CL_1 through rectifier RA and leading to terminal MLA_{15} of the electrical control circuits will take care of giving a substitute positioning authorization in those circuits. Indeed, the end of comparison pulse appearing, after a successful comparison, terminal CL_9 is conditioned by both numbers being correctly positioned in the shift registers. If the last number to be entered in the shift register and corresponding to the cheque immediately preceding the marker on that side, was not correct, this substitute authorization will therefore ensure that the splitting of the remaining sequences on the other side can still be performed. Rectifier RA is used to prevent that the positioning authorization normally given by the electronic control circuits should reach the mixer M_2 and cause undesired operation of relay A_{br} upon a normal cheque carrier being read.

Opening of break contact ab_2 applies a reset signal to terminal CL_{30} , as previously described, to enable the electronic control circuits to adapt themselves to the mere splitting of the remaining sequences on the other side. Opening of break contact ab_3 interrupts the ground at terminal CL_{26} to prevent recirculation of the numbers, as previously described, since comparisons between the two opposite sides should no longer be made while the remaining sequences on one side are being split between the two outputs. Opening of break contact ab_5 causes the release of relay Mr which closes its break contact m_1 to prepare the energisation of relay Mar which will however only take place upon the second marker reaching the opposite reading position resulting in both contacts ab_4 and bb_4 being closed.

The opening of break contact ab_6 prevents relay D_{jr} from being operated by the ground provided through make contact ia_1 . Indeed, irrespective of the condition

of relay *Iar*, since relay *Abr* has operated upon the arrival of a marker in the reading position on the A side, it must stay there until the second marker arrives into the reading position on the B side. During that time, only the eventual further cheques on the B input side should be advance, and this means that change-over contact *di*₁ in the break position should permit the transmission of a start of cycle pulse to terminal *CL*₃₄ to operate relay *Br*. On the contrary, if the first marker had entered the reading position on the other side, relay *Bbr* would have been operated and through make contact *bb*₆ would have caused the energisation of relay *Djr* to permit the start of cycle pulses to be applied to terminal *CL*₃₃ to cause the operation of relay *Ar*. Thus, from the moment a first marker enters a reading position, the further advancement of the cheques eventually remaining on the other side is made independently of the electronic control circuit (*Iar*).

Upon one of the relays *Abr* or *Bbr* being operated, during the next cycle, the start of cycle pulse at terminal *CL*₂₁ will pass through make contact *sc*₃ and break contact *mg*₉ to operate either relay *Acr* or relay *Bcr* respectively through make contacts *ab*₇ or *bb*₇. Either of these relays will only be temporarily operated during the start of cycle pulse PU (FIG 4) and these temporary operations are used to apply a reset signal either at terminal *CL*₂₉ due to the opening of break contact *ac*₁ disconnecting resistor *R*₆, or at terminal *CL*₂₇ due to the opening of break contact *bc*₁ disconnecting resistor *R*₄.

In the first case, the bistable device of the electronic comparator will be automatically and regularly reset to the condition indicating the advancement on the B side, and in the other case, regular resets to indicate advancement on the A side will be made as required. Thus, as far as the advancement of either one or the other input is concerned, as soon as a marker has entered a reading position, this is now totally independent of the electronic control circuit, since either relay *Iar* must automatically be released by every start of cycle pulse if relay *Abr* is energised, or relay *Iar* must automatically be operated at every start of cycle pulse if relay *Bbr* is energised. This is a duplicate for relay *Bbr* which is provided with two parallel operating paths if relay *Bbr* operates, and with a double opening of the operating path if relay *Abr* operates. This ensures that in no case will the marker stored in a reading position be allowed to leave that position before the other marker has also reached the opposite reading position.

Upon the second marker reaching the other reading position, relay *Mar* is energized through make contacts *ab*₄ and *bb*₄ in series and the results will be similar to those already described in connection with the initial condition of the two markers being located in the two reading positions *A'*₂ and *B'*₂ of the reverse sorting stage. When the two markers reach the reading positions of the normal sorting stage, there is however this difference that relay *Dmr* is immediately operated through make contacts *bb*₄, *ab*₄ and *ab*₁₀ in series, the ground provided through this connection being also applied to energise relay *Dar* immediately upon relay *Mar* operating and closing make contact *mg*₆. Hence, in the case of the normal sorting stage, as soon as the two markers are in their respective reading positions, they are immediately dispatched, one to the D and the other to the C output as required, without waiting for there being at least one cheque carrier at either input of the normal sorting stage.

This supplementary condition for the reverse sorting stage permits the markers to remain in the reading positions of their stage when the sort is finished, since the sorted cheque carriers being arrested in front of the normal sorting stage, none will pass the latter to send out the two markers which remain in the reverse sorting stage.

The sequence counter of four used for the reverse sorting stage only, in connection with the determination of the end of the sort will now be described.

It will be recalled that after the initial departure of the two markers from the reading positions of the reverse sorting stage, relay *Dnr* was temporarily operated, opened its break contact and therefore caused the release of the sequence counter comprising the eight relays *Yar*-*Yhr*. From that moment, the sequence counter of four was controlled by *Sqr* which is energised from terminal *CL*₈ through the amplifying device *SQ* similar to amplifying device *IA*. Terminal *CL*₈ is connected to terminal *CMP*₂₄ of the electronic comparator (not shown) and at this terminal, a long pulse of about 60 milliseconds appears every time there is a change of output at the reverse sorting stage. Hence, for every output sequence delivered by the reverse sorting stage, relay *Sqr* is momentarily operated. This results in the temporary closure of the make contact *sq*₁, which applies ground through break contacts *mg*₄ and *yb*₁ to relay *Yar* which is energised and locks through its make contact *ya*₁ in series with the winding of its helping relay *Ybr* and break contact *dn*₂ to the ground provided at terminal *CL*₂₅ by key *K*₃ in the released condition shown. Upon the reopening of make contact *sq*₁, relay *Ybr* is now energised in series with relay *Yar*. Change-over contact *yb*₁ in the make condition, now transfers the input operating circuit of the counter, consisting in make contact *sq*₁ in series with break contact *mg*₄, to the winding of relay *Ycr* through change-over contact *yd*₁ of its helping relay *Ydr*. Thus, relays *Yar* and *Ybr* forming the first stage of the sequence counter are energised by the first output sequence, relays *Ycr* and *Ydr* constituting the second stage of this counter will additionally be energised after the second output sequence has been delivered, and relays *Yer* and *Yfr* will then be energised, after three output sequences have been delivered by the normal sorting stage. Relays *Ygr* and *Yhr* will then be energised but only if there are more than four output sequences.

From this moment, the counter may be said to be saturated and further output sequences delivered by the reverse sorting stage can no longer modify its state. The important thing is to know that there are more than four output sequences which have been delivered by the reverse sorting stage, in which case the complete sort cannot be possibly finished in a single round trip through both stages of the sorting machine. Indeed, with the normal sorting stage being fed with more than four input sequences, it will at least deliver three output sequences, two on one side and one on the other, which the reverse sorting stage will not be able to merge into a single output sequence which could be taken out of the machine.

It should be noted that after the last output sequence is delivered by the reverse sorting stage, relay *Sqr* can no longer be temporarily operated to send a further pulse to the sequence counter of four, since at the moment the second marker comes into a reading position next to the first marker already located in the adjacent reading position, both the parallel contacts *ab*₈ and *bb*₈ are open to prevent current flow in *Sqr*. This is necessary since when both relays *Abr* and *Bbr* are operated, it will be recalled that the consequent openings of break contacts *ab*₂ and *bb*₂ would, together, set the electronic comparator to the end of sequence condition. Hence, as the second marker activates the photocells of the reading position in the same way as a cheque carrier, a comparator probe pulse is generated and the second marker thus causes a 60 milliseconds end of sequence pulse to appear at terminals *CMP*₂₄ and *CL*₈ to try and energize *Sqr*.

If there are no more than four output sequences, when relays *Abr* and *Bbr* are both energized by the two markers in their respective reading positions, relays *Ygr* and *Yhr* are therefore not energised and consequently an operating circuit is closed for relay *Mgr* by applying ground through make contacts *ab*₉ and *bb*₉ in series with break contact *yg*₂. Relay *Mgr* operates and locks to ground through its make contact *mg*₁. Through its make contact

mg_2 , an operating circuit is prepared for relay Zar , and eventually for relays Mhr and Aer . Through make contact mg_3 , the holding ground at terminal CL_{25} for maintaining the energisation of the operated relays of the sequence counter of four is duplicated independently of break contact dn_2 . Due to the opening of break contact mg_4 , the input circuit of the sequence counter of four is interrupted to ensure that from now on the state of this counter can no longer be modified.

Therefore, from the moment that relay Mgr has operated to close make contact mg_3 , the temporary operation of relay Dnr opening break contact dn_2 , and happening upon the second marker being sent off from its reading position, will not be able to affect the state of the sequence counter of four, which, otherwise, when there are more than four output sequences delivered by the reverse sorting stage during a sorting pass, results in the reset of this counter of which all eight relays would be de-energised.

In the case of the last sorting pass which is about to begin through both sorting stages and which is now assumed here, one can still distinguish two cases. Either three or four output sequences were delivered by the reverse sorting stage before the arrival of the two markers in their respective reading positions, or only two output sequences were delivered. In the first case, relays Ycr and Ydr are energised, and in the second case they are not. In the first case, the three or four sequences which will be fed to the normal sorting stage during the last round trip will necessarily appear as two sequences at the output of the normal stage and during the last pass, the reverse sorting stage will therefore effectively merge these two sequences into the single final sequence. In the second case however, the two sequences at the input of the normal sorting stage will appear as a single sequence at one or the other input of the reverse sorting stage, as the normal sorting stage performs its merging action. Since at the beginning of a sorting pass, after two markers have been sent away from their respective reading positions, an A cheque is first advanced to the reading position and then the first B cheque is advanced to the other reading position, the normal sorting stage will issue the single sequence of cheques but the reverse sorting would not be able to deal with it. There would be a waste of time, since the reverse sorting stage which in these circumstances has only to pass the final sequence delivered by the normal sorting stage would remain totally inactive while the normal sorting stage delivers that single output sequence. Only the arrival of the marker, the only article on one of the reverse sorting stages inputs could be used to eventually find out that there is merely the single wanted sequence at the input of that stage, and that this single final sequence must still be passed through that stage to reach the common input/output position of the sorting machine. As will be described, this delay is avoided due to relay Ycr being de-energised in these circumstances and eventually permitting the operation of relay Mhr .

In the two cases considered, i.e. on the one hand two output sequences, or on the other hand three or four output sequences, upon the first cheques having been delivered by the normal sorting stage, and having travelled through the corresponding output transverse conveyor sending them to one of the two inputs of the reverse sorting stage, relay Adr or Bdr will be energised and in the manner previously described will result in the two markers being sent away from their reading positions in the normal sorting stage, one towards the D output and the other towards the C output. Upon the second marker leaving the reading position, contacts ab_5 and bb_5 will be closed causing the energisation of relay Mr and the subsequent release of relay Mar as previously described. But, in addition to the operation of relay Mr , relay Zar also operates through make contact mg_2 .

The opening of break contact za_1 interrupts the po-

tential of -25 volts previously connected to delay device D_1 through resistor R_7 . This delay device D_1 is designed to produce an output signal say 10 seconds after the opening of the break contact za_1 , this output signal causing the operation of relay Zbr connected at its output. For instance, D_1 may comprise a pentode amplifier of which the cathode is grounded through the winding of Zbr . The input grid circuit of this pentode may include a condenser which is normally charged to -25 volts through resistor R_7 . Normally the potential of -25 volts appearing at one terminal of this condenser is connected to the grid of the pentode which is therefore cut-off. This condenser plate is also permanently connected through a suitable resistive circuit, so that upon the opening of break contact za_1 , the grid potential will gradually rise whereby the required delayed operation of relay Zbr may be obtained.

This delay starting from the moment the two markers are sent away from the reverse sorting stage is designed to permit them to advance on their respective transverse conveyors leading to the input positions A_4 and B_3 of the normal sorting stage NS (FIG. 1), so that they are sufficiently near these two input positions by the time relay Zbr operates. Then, make contact zb_1 applies ground to relay Zcr which operates and brings the stops down in front of the input positions A_4 and B_3 , so that the cheque carriers which will now come out of the reverse sorting stage RS will be arrested by the stops ready to be taken out of the sorting machine. As soon as relay Zar is operated due to the departure of the second marker, break contact za_2 opens and prevents the start of cycle pulses regularly applied at terminal CL_{19} from eventually reaching terminals CL_{33} or CL_{34} to cause the advancement of the cheques at the inputs of the reverse sorting stage, and which could otherwise be possible as soon as relay Mar releases and closes its break contact ma_8 . It is only after the operation of relay Zcr , subsequent to the markers having arrived near to the input positions A_4 and B_3 that make contact zc_4 will be closed to bridge the now open za_2 break contact.

This bridging action will however only be effective if it is assumed that the series break contact mh_3 is still closed and accordingly that relay Mhr has not energised simultaneously with Zar and Mr due to there having been only two output sequences delivered by the reverse sorting stage. If three or four output sequences were delivered, from the moment relay Zcr is operated, the start of cycle pulse at terminal CL_{19} is ready to cause the advancement of the cheque carriers through the reverse sorting stage as soon as they start to be delivered on both output sides of the normal sorting stage.

On the other hand, if only two output sequences were delivered by the reverse sorting stage, relay Mhr operates together with relay Zar , and opens make contact mh_3 , thereby preventing the closure of make contact at zc_4 from being effective to permit the start of cycle pulse to reach the armature of change-over contact d_1 . But instead, through make contact zc_6 , the armature of change-over contact ae_2 of relay Aer in either position, and either make contact mh_5 or mh_6 , the start of cycle pulse at terminal CL_{19} will respectively be able to reach terminals CL_{33} or CL_{34} to cause the advancement of the cheques appearing either at the A or the B input of the reverse sorting stage. If the single output sequence delivered by the normal sorting stage is sent towards the input position A'_4 (FIG. 1) of the reverse sorting stage, the cheques will be automatically advanced through that input position as soon as they arrive without waiting for the hypothetical series of cheques at the other input. On the other hand, if the single output sequences delivered by the normal output stage is sent towards input position B'_3 of the reverse sorting stage, the first cheque carrier arriving next to that position would cause the energisation of relay Bdr as previously described. Hence,

of the temporarily closed make contact bd_2 through make the closure of make contact bd_2 will apply ground to operate relay Aer which locks to ground independently contact ae_1 . Relay Aer being operated, change-over contact ae_2 moves to the make condition and the start of cycle pulses at terminal CL_{19} will now be dispatched to terminal CL_{34} through make contact mh_6 , also to cause the immediate advancement of the single sequence appearing at the B input of the reverse sorting stage.

In both cases, another effect of the operation of the stop relay Zcr , which locks to ground through make contact zc_1 , is to move change-over contact zc_2 to the make condition. Gate G_1 has one of its inputs connected to terminal CL_{13} which is controlled by a photocell arrangement arranged along the transverse conveyor linking output position D' to input position A₄ (FIG. 1). It is located towards output position D' at a distance from the stop controlled by relay Zcr which corresponds to about half the overall thickness of the complete lot of cheque carriers inserted in the sorting machine. The beam of light striking the photocell (not shown) is substantially perpendicular to the direction of advancement of this transverse conveyor, and this beam of light will therefore be interrupted upon there being at least about half the total number of cheque carriers packed on the D output lane from the reverse sorting stage RS (FIG. 1), the first cheque carrier being pressed against the stops controlled by relay Zcr . At this moment, the mass of cheque carriers will permanently interrupt the beam of light striking the photocell. Indeed, as long as the cheque carriers flow past the photocell arrangement, without being actually closely stacked together in front thereof, the temporary interruption of the beam of light can be made without effect on the output of the photocell arrangement if the latter is provided with a suitable time constant, so that it can only react after an interruption of the beam of light for a certain interval of time.

Normally, the beam of light which illuminates the photo-cell causes an activating signal to appear at terminal CL_{13} . As there is also an activating ground signal transmitted through resistor R_8 at the other input of gate G_1 , the latter delivers an activating output signal which, from the moment relay Zcr operates is transmitted to the input of the amplifying device D to cause the operation of relay Odr . Therefore, irrespective of the initial condition of this relay at the time Zcr energises, the cheques which will be allowed to go out from the reverse sorting stage RS some 10 seconds after the two markers, will necessarily be delivered to the D output. If relay Odr was in the released condition at the time Zcr operates, an energising circuit is closed for relay Zdr through break contact od_2 in series with make contact zc_5 . But, relay Zdr is slow to operate, and accordingly it has no opportunity to energise at that moment, since relay Odr quickly energises to open the operating circuit of relay Zdr at break contact od_2 .

From the moment relay Zcr operates leading also to the operation of relay Odr , an operating circuit is closed for relay Dar , ground being applied through make contacts mh_2 and zc_3 in series with break contact bb_{10} and change-over contact od_1 in the make condition. Therefore, relay Dar being permanently operated, the cheques flowing through the reverse sorting stage will indeed be accumulated on the D output conveyor. This substitute ground provided for the output relays Car and Dar through make contact mh_2 is mainly to replace the ground normally provided by the electronic control circuit (not shown) producing the operation of relay Okr and the closure of make contact ok_2 , as well as the operation of relay Otr , and the closure of make contact ol_1 , after a successful comparison has been made. Indeed, in the present case of a single sequence already appearing at one of the outputs of the normal sorting stage, there are only cheques on one side, and the electronic control cir-

cuits are arranged so that they do not deliver this signal to operate relay Okr unless both numbers are correctly positioned. If the last number to be stored on the opposite side to that on which the cheques are now entered, 5 was not correct, relay Okr would not be operated. The present scheme makes therefore the operation of the output relays independent of the electronic control circuits. This will happen only if the reverse sorting stage delivered only two output sequences prior to the last round trip. In such a case, the single sequence going through the reverse sorting stage during the last round trip must no longer be sorted and the circuit just described therefore prevents the electronic control circuit, controlling relay Okr , from being effective since this is no longer needed. Any faulty influence of the electronic control circuit, preventing the beginning of the final single output sequence from reaching the D transverse conveyor is again avoided.

Still for the case when the sequence counter detected 20 only two sequences at the end of a double sorting pass, upon relay Mhr having been operated and relay Mar having been subsequently released due to the operation of relay Mr (departure of the two markers) relay Mjr was operated through break contact ma_{11} and make contact mh_1 and locked through its make contact mj_1 . Accordingly, make contact mj_2 is now closed.

This has the advantage of maintaining this substitute ground for the output relays Car or Dar when the marker comes into the reading position B'_2.

30 Assuming that a single sequence is fed to the A input of the reverse sorting stage, as some cheques still pass through that stage, the marker on the other side, the B side, may arrive next to the input position B'_3 and cause the operation of relay Bdr and in turn, that of Aer . 35 Due to change-over contact ae_2 moving to the make position, the advancement of the cheques at the A input will now be stopped until the marker on the B side reaches the reading position B'_2 and causes the operation of relay Bbr moving change-over contact bb_{10} to the make position. 40 The operation of relay Bbr opens break contact bb_5 thereby releasing relays Mr , Zar , Mhr and Aer but the opening of make contact mh_2 will remain without effect, the substitute ground being still provided through make contact mj_2 . This ensures that the single sequence of 45 cheques continues to be delivered at the output of the reverse sorting stage.

From the moment that a marker is in the reading position such as B'_2, relay Mhr being released, the start of cycle pulse CL_{19} will again reach either terminal CL_{33} 50 or CL_{34} through break contact mh_3 . Thus the advancement of one or the other side is again under the control of relay Djr . It is to be noted that this relay together with relays Dmr and Dnr had their battery connections interrupted by the opening of break contact mh_4 as long 55 as relay Mhr was energised. This is merely a safeguard to ensure that these relays can never be energised to control the advancement of one or the other input, while this advancement is controlled through the start of cycle pulse at terminal CL_{19} passing through make contact zc_6 . 60 In the present case since Bbr was operated, Djr is energised through make contact bb_6 , and the single sequence of cheques on the A side continues to advance. In the reverse case, when a single sequence of cheques appearing at the input of the reverse sorting stage is on the B side, if the 65 marker is eventually dispatched to the A input while the cheques are still passing through the reverse sorting stage, this marker on the A side will be unable to go through input position A'_4. This is because relay Aer was operated and locked due to relay Bdr being energised by the first cheque at the B input, and accordingly the start of cycle pulses continue to be transmitted to terminal CL_{34} to continue the advancement of the cheques, the marker on the A side remaining next to the input position A'_4. This 70 means that relay Mhr remains operated until the marker 75

on the B side reaches the reading position B'_2 , operates Bbr , causes the release of several relays including Mhr and the operation of relay Djr through make contact bb_6 to finally advance the marker on the A side to the reading position A'_2 .

After a sufficient number of cheques, i.e. about half the total lot, have been accumulated on the output conveyor on the D side of the reverse sorting stage, the photo-cell arrangement will no longer be able to supply an activating signal at terminal CL_{13} and consequently relay Odr will be released. From this moment, the cheques will be delivered to the C output of the reverse sorting stage, this time not because there is a change of sequence but merely in order to split the distribution of the sorted cheques between the two conveyors at the input of the normal stage. The release of relay Odr closes an operating circuit, through break contact od_2 , for slow to operate relay Zdr which eventually energises and applies the inhibiting signal of -25 volts through its make contact zd_1 to the input of gate G_1 connected to resistor R_8 . This is in effect a locking action for gate G_1 designed to prevent an eventual renewed delivery to the D output side. This could for example happen if the sorted load of cheques at the D output was removed while the remainder of the sorted cheques was still being accumulated at the C output. Then, G_1 would again give an output signal which would cause an undesired shift back to the D output.

At the end of the sort, when both markers are in their respective reading positions A'_2 and B'_2 , relay Mar energises as previously described and causes the release of relay Mjr .

If during the last pass, the normal sorting stage delivers two sequences, one on each side, the operations will be substantially as detailed above, except of course that as in the case of a normal sorting pass, the first sequence delivered to one input of the reverse sorting stage will have to wait until the other sequence arrives at the other input. Since relay Ycr is energised, neither relay Mhr nor Aer can be operated, and though relay Odr will first be operated and then released under the control of the forced splitting arrangement described above, the actual operation of Dar and then Car will be controlled by contacts ok_2 and ol_1 , while the final advancement of the cheques through the reverse sorting stage will be controlled by Djr .

Various miscellaneous features will now be discussed.

The reject counter of three receives a pulse through break contact ol_2 , at the start of each cycle, whenever relay Olr was not energised during the previous cycle, thus indicating a faulty condition. It will be remarked that at certain moments, relay Iar may be in the energised or released condition to indicate the advancement of the cheques at the A or at the B input of a stage respectively, but without there being actually cheques ready to advance into the corresponding reading position. This may happen for example at the beginning of a sorting pass. If such empty positions occur, it is undesirable to send a reject pulse due to the non-operation of relay Olr during a cycle and this is prevented by the open make contacts aa_2 and ba_2 which are only closed upon there actually being a cheque in the reading position. This circuit to the reject counter of three is also interrupted by break contact ma_9 as soon as relay Mar has energised to indicate that the two markers have reached their respective reading positions. Until both markers have left the reading positions, relay Olr cannot be energised and one should therefore avoid sending a reject pulse. As soon as a single reject pulse occurs at a sorting stage, relay Rjr operates temporarily in addition to the counter of three and causes the energisation of relay Rkr by closing its make contact rk_1 . Relay Rkr operates and locks through its make contact rk_1 in series with break contact sa_2 . This last operated relay may control a lamp circuit (not shown) to indicate that there has been at least one reject at the stage concerned during the sorting operation.

If there are three consecutive rejects, the third reject pulse will cause the operation of relay Xfr which closes its make contact xf_2 to operate relay Rlr . Relay Rlr is a general release relay which opens its make contact rl_1 , thereby preventing the start of cycle pulse from reaching terminal CL_{33} or CL_{23} to continue the advancement of the cheques. From the moment the release relay Rlr operates at one stage, that stage is effectively blocked since the cheques can no longer advance through it.

It should be noted that the interruption of this advancement circuit does not apply to the reverse sorting stage in case relay Mhr is energised to indicate that during the last sorting pass only a single final sequence of cheques streams out of the normal sorting stage. In such a case, the cheques passing through the reverse sorting stage are not actually sorted therein but merely transferred to the final output position.

It will be recalled that the cheque is sent to the reject position if it was badly read, while on the other hand, if there is an error after the electronic control circuits have recirculated the account numbers corresponding to the two cheques in the two reading positions of any stage, a pulse appears at terminal CMP_6 to be applied to terminal CL_{10} , causing the operation of relay Err and the subsequent reset of the electronic control circuits. In such a case, the actions are equivalent to those happening at the beginning of a sorting pass and both cheques will be rejected. Even this double reject will be insufficient to cause the operation of relay Rlr and stop the corresponding sorting stage, but if this type of error is consecutively repeated, then the sorting stage concerned will cease to function. Hence, errors of a transient nature will generally not stop a sorting stage, whereas the consecutive repetition of errors generally indicating some permanent fault would result in the sorting stage concerned being disabled.

Various lamps (not shown) may readily be added to the circuits described in order to give suitable indications on the operation of the machine to an operator. Apart from the lamp mentioned above and which may be lighted due to the operation of relay Rkr to indicate that there has been at least one reject at the corresponding stage, one may also add other lamp circuits to indicate for instance that the machine is on, or is out of order. Moreover, it would be useful to include a lamp which is lighted to indicate that the machine is performing the last sorting pass and that the sorted cheques will soon be available. This last pass lamp circuit may be energised upon relay Zar being operated, a make contact (not shown) of this relay used to close the lamp circuit being paralleled with a further make contact (not shown) of relay Zcr . This is necessary, since although relay Zar operates first, in the reverse sorting stage, it will subsequently be released when the first marker comes into its final reading position in the reverse sorting stage, whereas relay Zcr remains locked in the operated condition at the end of the sorting operation.

For each sorting stage or for both, a lamp may also be added to be lighted upon relay Err being operated, to indicate that a cheque carrier is not correctly centered in one of the various positions of the sorting stages. Finally, in both stages, the relays Rlr may also light a corresponding lamp when they are operated to indicate that the corresponding sorting stage has been disabled.

Whenever a fault has occurred, the reset push buttons K_0 should always be operated to energise the corresponding relays Sar with the consequences previously explained. In particular, this action will permit the recognition of the fact that, at the time of the fault, e.g. a power failure, a marker was standing in one of the reading positions. Then, the closure of make contact sb_1 will produce a substitute reading authorization for the marker standing in the reading position and the corresponding relay Abr or Bbr will be energised. This facility is due to the cheque carriers acting on the photocell,

when they stand in the reading positions, i.e. ordinary carriers block all three photocells and markers the upper two only.

A few additional keys have been shown in FIG. 3. A first key of which the function has not yet been described is K_3 which may be used for merging operations, when there are only two sorted lots of cheques which have to be merged together in a single sorting pass. Actuation of key K_3 will remove the ground normally applied at terminal CL_{25} with the result that none of the eight relays $Yar-Yhr$ of the sequence counter of four can remain energised. On the other hand, ground will be applied instead to terminal CL_{24} , leading to relay M_{gr} which will therefore be energised and which will lock as previously described. Hence, shortly after the beginning of a merging operation, as the first cheque comes out of the normal sorting stage, the two markers normally stored in the reading positions of the reverse sorting stage will be sent off resulting in break contacts ab_5 and bb_5 closing an operating circuit for relays M_r , Zar and M_{hr} , the latter since relay Ycr of the sequence counter is necessarily in the released condition. Hence, conditions are exactly as they were in the case of the last sorting pass for a normal sorting operation, with only a single sequence of cheques coming out of the normal sorting stage.

Of course, additional facilities can be provided. For instance, if the need for merging four individually sorted lots of cheques would arise frequently, the sorting machine could readily be adapted to such a function by merely conditioning the circuits so that both the normal and the reverse sorting stage perform a merging operation, with the result that the full merged lot of cheques would also be obtained after a double sorting pass, i.e. a single round trip.

Key K_4 may be used to interrupt the connection between terminals CL_{16} and CL_{17} whereby the operation of the error relay Err will be ineffective to cause the reset operation for the electronic control circuits normally made during the energisation of relay Sbr . The operation of relay Err indicates that a fault has occurred after the two account numbers of the cheques standing in the two reading positions have been recirculated, and in such a case both cheques must be rejected, and the circuits should normally be conditioned so that the situation is now similar to that occurring at the beginning of a sorting pass. Avoiding such a reset by the opening of key K_4 may be useful to permit an examination of the electronic circuits when such a fault occurs, and especially when it is not the first time that it occurs, i.e. not merely a transient error.

Depressing key K_5 interconnects terminals CL_{39} and CL_{40} with the result that a stop relay Str is instantly energised by the first reject pulse able to pass through break contact ol_2 . The operation of relay Str for the stage concerned opens break contact st_1 and the action is therefore similar to that of the operation of relay R_{hr} when three consecutive rejects have occurred, and leading to the opening of break contact rl_1 . This immediate stop of the starting stage by the operation of relay Str at the first reject, is useful to permit an examination of the electronic control circuits and more particularly the information stored in the shift registers. Indeed, in the case of a normal reject due to a cheque having been badly read as it entered the reading position, spurious pulses may have caused an incorrect registration of the account number and the nature of the fault can then be readily examined.

Keys K_6 and K_7 when operated, respectively interrupt the connections between terminals CL_{27} and CMP_{16} on the one hand and terminals CL_{29} and CMP_{22} on the other. In this manner, a manual reset causing the advancement of the A or the B input respectively, may be obtained. This facility may be desirable in certain circumstances, particularly in the case of faults.

Finally, although this has not been shown, the starting key K_1 may be duplicated by a parallel start push button which may conveniently be used to manually operate the machine in a step by step fashion. With a little skill an operator can readily advance cheques one at a time and this will again be found useful in helping to determine faulty conditions.

It will be appreciated from the previous description that the use of two markers in a sorting machine of the general type disclosed in our U.S. patent application, Serial No. 805,800, previously referred to, and using only two stages looped on one another has outstanding advantages.

The main advantages are that the residual sequences occurring at one input of the normal sorting stage after the other input has become empty during the normal sorting stage are immediately split between the two outputs of the normal sorting stage as desired. Moreover, the markers not only achieve the splitting of the residual sequences but they also automatically provide for load balancing. In other words these residual sequences will always be alternately distributed to the two outputs of the normal sorting stage before the sequences resulting from the first double pass have an opportunity to go through the normal sorting stage for the second time. Further, the use of the markers permits foreseeing the end of the sorting operation in advance, and therefore stopping the sorted documents in locations particularly suitable for their easy removal from the machine. Moreover, the use of the markers also permits the sorted documents ordered in a single final sequence to be distributed at the input of the normal sorting stage where the lot of documents to be sorted is initially inserted, thereby facilitating the feed of the sorting machine and the delivery of the sorted documents. Additionally, in a two-stage loop sorting machine wherein the documents are only subjected to translation movements, this means that after sorting, it will always be the same side of the documents which will be in front.

Also, the built-in feature for the markers is most convenient, since no attention on the part of the operator is required, the markers being always positioned in the required manner behind the two half lots of documents to be sorted.

The nature of the markers also facilitates the design of the sorting machine, since these markers have the same shape as the ordinary document carriers. They can readily go through the same mechanisms as these document carriers, and moreover, the detection circuits do not need to include special electronic circuits to recognize the markers, simple arrangements using mainly conventional telephone type relays can be used.

Also, a corollary of the ability to foresee the end of the sorting operation is that the final sequence may then be split between the two inputs of the normal sorting stage, whereby the sorted documents can be taken out of the machine in two half lots corresponding in size to the half lots with which the machine is initially fed.

The fact that the markers always permit the distribution of the sequences between the two outputs during the whole sorting operation, makes the machine less sensitive to occasional faults in the electronic control circuits.

In our U.S. patent application last referred to, an efficiency of operation was defined and some comparative figures were given between a sorting machine with ten cascaded stages and a two-stage loop sorting machine, including the case where the latter is provided with load balancing means which are effective only at the beginning of the sorting operation for the normal sorting stage. Using markers, the load balancing feature is permanent during the whole sorting operation and the following table shows that the efficiencies of a two-stage loop sorting machine using markers and a two-stage loop sorting machine using initial load balancing means are comparable.

Initial loads at the two inputs	{ 512(1) 512(1)	250(2) 250(2)	251(2) 261(2)	246(2) 266(2)	236(2) 276(2)	216(2) 296(2)	100(2) 120(2)
Two-stage (with load balancing during the first sorting pass), percent	84	90	76	77	78	70	63
Two-stage (with continuous load balancing by means of markers), percent	91	86	75	75	76	76	75

The various columns in the above table identify the cases considered. The numbers before the brackets refer to the number of sequences initially delivered at each input of the normal sorting stage while the number between the brackets identify the length of the initial sequences which is assumed to be the same for all sequences. Thus the first column refers to an input load of 1024 documents initially fed to the normal sorting stage in two equal half loads of 512 documents at each input and said documents being initially ordered exactly in the reversed order than the desired one since each sequence comprises only one document.

While the principles of the invention have been described above in connection with specific apparatus, it is to be clearly understood that this description is made only by way of example and not as a limitation on the scope of the invention.

We claim:

1. In a sorting machine having two sorting stages, each with two inputs and two outputs, the two inputs of one stage being respectively fed by the two outputs of the other stage and vice versa, and with the articles to be sorted initially applied to the two inputs of a sorting stage in lots of substantially equal sizes to be sorted through each stage in accordance with their sorting characteristics, e.g. by merging sequences of like rank appearing at the two inputs and dispatching the merged sequences alternately to one and the other output of the sorting stage, the combination comprising a pair of markers adapted to go through said two sorting stages in the same way as the articles, said markers being respectively placed behind two lots of articles initially applied to the two inputs of a sorting stage, readable means on said markers for distinguishing said markers from said articles, and an electrical control circuit for each sorting stage including means responsive to a reading of said distinguishable means for causing said markers to be dispatched to opposite outputs as they pass through each stage.

2. In a sorting machine having two sorting stages, the combination, as claimed in claim 1, in which the control circuits further comprise means responsive to a first marker reaching a first sorting stage for causing the eventual sequences of articles remaining at the input of the second sorting stage to be alternately dispatched to the two outputs of said second sorting stage until the second marker reaches said first sorting stage, and means responsive to said second marker reaching said first sorting stage for causing said two markers to be dispatched through said first sorting stage, one towards one output and the other towards the other output.

3. In a sorting machine having two sorting stages, the combination, as claimed in claim 2, in which the control circuits further comprise means responsive to the last sort of said machine to cause said two markers to be retained in respective storage positions in one of the two sorting stages, whereby they will be at the same positions at the start of a new sort.

4. In a sorting machine having two sorting stages, the combination, as claimed in claim 3, in which the control circuits further comprise means responsive to an article reaching one of the two inputs of the stage initially containing said two markers for dispatching said markers to the two outputs of said stage, and means responsive to the completion of the sort for stopping

said articles from flowing through the other stage, whereby upon the final single sequence of articles having been delivered through said one stage, said two markers will be returned to and stay in their initial storage positions.

5. In a sorting machine having two sorting stages, the combination, as claimed in claim 3, further comprising a sequence counter in the electrical control circuit for the one stage in which the two markers are initially stored adapted to count the number of output sequences from said one stage between two successive passages of said two markers through said one stage, means for resetting said counter each time said two markers pass said one stage, means responsive to the action of said counter to indicate whether or not no more than four output sequences have flowed through said one stage during a round trip to said two markers, stop means responsive to said sequence counter indicating no more than four output sequences for stopping said articles on their way to the corresponding inputs of the other stage, after said markers having gained access to said other stage but prior to the articles behind said markers being allowed to go through said one stage, whereby the final output sequence of articles will be prevented from passing through said other stage and may be positioned ready to be taken out of the sorting machine.

6. In a sorting machine having two sorting stages, the combination, as claimed in claim 1, further comprising two reading positions at each stage, a magnetic reading head at each reading position for reading magnetically encoded signals inscribed on the articles, at least three photocell devices at each reading position arranged to be affected by portions of said articles and markers, said control circuits including means responsive to a signal from a first photocell device for establishing a distinction between an ordinary document and a marker, and means responsive to successive signals from the next photocell devices as the article or marker moves through the associated reading position for indicating the beginning and the end of a reading operation for generating an authorizing pulse for transmittal to electronic reading circuits allowing them to record the magnetically encoded signals at the output of said reading heads.

7. In a sorting machine having two sorting stages, the combination, as claimed in claim 6, in which the photocell devices are arranged so that the first photocell device delivers the signal distinguishing an ordinary article from a marker before said article or marker is able to produce the signals by means of said second and third photocell devices.

8. In a sorting machine having two sorting stages, the combination, as claimed in claim 7, in which the articles are transparent document carriers each provided with a piece of magnetic tape on which the sorting information of the document, together with the eventual satellite information is inscribed, and in which the markers are constituted by document carriers identical to the ordinary ones but without said piece of magnetic tape, whereby the first photocell device is adapted to distinguish the presence or the absence of said magnetic tape to deliver a signal characterizing a document carrier enclosing a document or a marker.

9. In a sorting machine having two sorting stages, the combination, as claimed in claim 1, in which the control circuits include means for detecting a faulty article, said machine having means at each stage responsive to said detecting means for rejecting said faulty article by dispatching it in a predetermined reject path, means for counting the number of rejected articles delivered to said reject path, and means for stopping the operation at a sorting stage when the number of rejects thereat exceeds a predetermined maximum.

10. In a sorting machine having two sorting stages, the combination, as claimed in claim 9, in which means is provided for using the same counter used to count rejected articles which may be detected when an incoming article

is compared with the outgoing article which it replaces, and also to count the twin rejected articles which may be detected when two articles having already been read are compared with one another to determine which should be the first to go out of the sorting stage concerned.

11. In a sorting machine having two sorting stages, the combination, as claimed in claim 10, further comprising detection means along the first output of the stage to which the articles forming the final sequence are always delivered for determining when substantially half the total lot of articles has been delivered to that output, and means in said detection means for thereupon causing said stage to deliver the remaining half of articles to the other output, whereby the final sequence of articles is divided at the two outputs.

12. In a sorting machine having two sorting stages, the combination, as claimed in claim 6, further comprising means responsive to restarting the machine after the advancement operations at any of the two stages of the machine is stopped because of a fault, for causing the photocell arrangements at the stage concerned immediately to distinguish between articles or markers being located in the reading positions of that stage.

13. In a sorting machine having two sorting stages, the combination, as claimed in claim 5, further comprising means responsive to the sequence counter associated with one stage having determined that the other stage will deliver the single final output sequence of articles, for causing said one stage which is normally adapted to prevent the advancement of articles at one of its two inputs when the other input is empty, nevertheless immediately to pass the articles of said single final sequence through said one stage as soon as they arrive at one input.

14. In a sorting machine having two sorting stages, the combination, as claimed in claim 1, in which means is provided in the control circuits for transmitting a signal whenever one of said markers has reached the sorting stage concerned and waits for the arrival of the other marker at this stage, which signal may be used for automatically avoiding the comparison which normally takes place between the numbers of two articles having come from the two inputs, in order to determine which is the first to go through the stage.

15. In a sorting machine having two sorting stages, the combination, as claimed in claim 1, in which the control circuits further comprise means responsive to the last sort of said machine to cause said two markers to be retained in respective storage positions in one of the two sorting stages, whereby they will be at the same positions at the start of a new sort.

16. In a sorting machine having two sorting stages, the combination, as claimed in claim 6, in which the articles are transparent document carriers each provided with a piece of magnetic tape on which the sorting information of the document, together with the eventual satellite information is inscribed, and in which the markers are constituted by document carriers identical to the ordinary ones but without said piece of magnetic tape, whereby the first photocell device is adapted to distinguish the presence or the absence of said magnetic tape to deliver a signal characterizing a document carrier enclosing a document or a marker.
